UNITED STATES PATENT OFFICE.

JONATHAN PETERSON, OF BROOKLYN, NEW YORK.

LABELING-MACHINE.

1,317,389.

Specification of Letters Patent. Patented Sept. 30, 1919.

Application filed April 23, 1917. Serial No. 163,968.

To all whom it may concern:

Be it known that I, JONATHAN PETERSON, a citizen of the United States, residing at 746 St. Marks avenue, Brooklyn, New York, in the county of Kings and State of New York, have invented certain new and useful Improvements in Labeling-Machines, of which the following is a specification.

This invention relates to improvements 10 in labeling machines and more particularly to machines for applying labels, etc., to containers, boxes, etc.

The general objects of the invention are to provide apparatus embodying mechanisms so correlated in operation as to provide individual manipulation of each label and container during travel through the apparatus and, at the same time, permit such individual manipulations to be provided in close succession with a resultant large capacity. In practice, machines of the type herein disclosed have delivered labeled containers at a rate in excess of 300 containers per minute.

Other objects are to provide a structure 25 of comparatively compact form and having mechanisms each of which performs its individual functions in rapid succession with the several mechanisms correlated to produce these successive cycles of manipulation with each cycle complete as to the time necessary to insure proper label application.

To these and other ends, the nature of which will be readily understood as the invention is hereinafter disclosed, said invention consists in the improved construction and combination of parts hereinafter fully described, illustrated in the accompanying drawings, and more particularly pointed 40 out in the appended claims.

In the accompanying drawings in which similar reference characters indicate similar parts in each of the views:

Figures 1 and 1^a combinedly show a plan 45 view of the machine with portions omitted for the sake of clearness.

Figs. 2 and 2^a combinedly show a side elevation of the machine of Figs. 1 and 1^a, parts omitted in Figs. 1 and 1^a being included, parts being broken away to illustrate structural details.

Fig. 3 is a perspective view showing the feeding end of the machine.

Fig. 4 is a perspective view of the end 55 of the machine opposite that of Fig. 3.

Fig. 5 is a view partly in elevation and

partly in section of an intermediate portion of the machine.

Fig. 6 is a view partly in elevation and partly in section of the end of the machine 60 shown in Fig. 4, showing the final label wiping structure in position.

Fig. 7 is a view partly in elevation and partly in section of portions of the label feeding mechanism.

Fig. 8 is a sectional view taken on line 8—8 of Fig. 7.

Fig. 9 is a view in elevation of a portion of the label supply drum.

Fig. 10 is a detail view of a label-retaining element employed in connection with the drum of Fig. 9.

Fig. 11 is a perspective view of a follower 70 employed in the compartments or pockets of the label supply drum.

Fig. 12 is a longitudinal section of the follower of Fig. 11.

Fig. 13 is a view partly in section and partly in elevation of mechanism for controlling the label segregating and feeding 80 mechanism of the label feed drum or picker.

Fig. 14 is a view partly in elevation and partly in section of the structure of Fig. 13, the view being at approximately right angles to Fig. 13.

Fig. 15 is a sectional view taken on line 15—15 of Fig. 14, showing the parts in position when the machine is at rest.

Fig. 16 is a view similar to Fig. 15, with the parts moved to the positions occupied 90 when the machine is in operation.

Figs. 17 and 18 are views in end and side elevation, respectively, of the key or valve member employed in controlling the operation of the label picker.

Fig. 19 is a view in elevation of a rotatable element active in feeding the labels.

Fig. 20 is a view partly in elevation and partly in section showing an automatic detector mechanism for controlling certain 100 operations of the label carrier mechanism.

Fig. 21 is an elevation taken at right angles to Fig. 20.

Fig. 22 is a detail sectional view of parts of detector mechanism.

Figs. 23 and 24 are sectional views indicating a valve structure in different positions.

Fig. 25 is a diametrical sectional view taken through the container feeding mechanism.

Figs. 26 to 28 inclusive are cross-sectional

views taken on lines 26—26, 27—27 and 28—28, respectively, of Fig. 25.

Fig. 29 is a sectional view taken on line 29—29 of Fig. 25.

5 Fig. 30 is a detail perspective view of a block structure employed in the container feeding mechanism.

Fig. 31 is a detail view, partly in section and partly in elevation showing the manner 10 in which the container is supported during the label affixing operation.

Fig. 32 is a cross-sectional view taken on line 32—32 of Fig. 6.

15 Figs. 33 to 44 inclusive, indicate diagrammatically successive stages of the label applying and affixing operations.

The general type of invention disclosed herein is applicable for applying labels to 20 containers of various configurations, as for instance, boxes having circular contours, or boxes having contours more or less angular in type, or with rounded corners and to which a label is to be applied with the label extending on more than one face of the box.

25 Obviously, the container may have other than a box form. However, for the purpose of illustrating the general principles of the invention, I have shown the embodiment as adapted to apply labels to the periphery of 30 a container having its label-receiving face of circular contour, it being understood, of course, that changes in construction may be required where a different configuration is employed, although the disclosed machine 35 will operate in connection with contours which are not truly cylindrical, as for instance, a more or less oval contour.

As heretofore pointed out, the machine is 40 designed more particularly to provide for large output or capacity, and to produce this result it is desirable that hand manipulation of the labels and containers be reduced to a minimum. This is provided by the use of various mechanisms, or instrumentalities 45 which are correlated in operation in such manner as to provide practically a continuous travel of labels and containers, with the mechanisms timed to produce such general result.

50 Before giving a detail description of operating parts, I will first give a brief outline of the general operation of the machine and especially of the label delivering, adhesive applying, label positioning and affixing steps 55 of the general cycle through which each container and its label passes.

The labels are carried by a rotatable drum 60 having a plurality of pockets or compartments each carrying a supply of individual labels which have their directions of length extending transverse to the general direction of label travel through the machine, the labels being free from adhesive coating. Rotation of the label supply drum causes 65 the several pockets to be successively brought

into the sphere of operation of a label segregating drum or label picker rotatable synchronously with the label supply drum and which is adapted to remove an individual label from each pocket in succession and 70 carry it to and deposit it on the adhesive-applying mechanism. The specific structures and operations of these drums will be presently described.

The adhesive-applying mechanism is in 75 the form of traveling belts, these belts being preferably endless and having flights which become active in the application of the adhesive to the label and serve to carry the label to its point of application to the container. In the particular embodiment shown, the adhesive-applying belts are three in 80 number, arranged as shown in Fig. 33, the outer belts, a and a' being spaced apart, a third belt a^2 being located between the outer 85 belts. These belts have their flights arranged in such manner as to provide the application of a coating of adhesive material on that surface which is uppermost and in opposition to the label segregating drum or 90 picker at the time when the label is to be deposited on the belts. Fig. 33 indicates the arrangement of the belts, and shown as having a layer of adhesive b , while Fig. 34 indicates the position of a label c on these 95 coated faces. As will be seen, the individual belts provide stripes or zones which extend transverse to the direction of length of the label, but the close relation of the belts at this time is such that but a slight portion of 100 the label is left free from adhesive. As will be understood, the center of the label and its opposite ends are in direct contact with these coated belt faces.

Advancing travel of the belts a , a' and a^2 105 carries them to a point where two endless belts d and d' , traveling at the same speed with belts a' and a^2 , pass into contact with the upper face of the label, as in Fig. 35. Belts d and d' are arranged opposite to belts 110 a and a' and are preferably of less width than said belts, the inner edges of the opposing belts being practically on the same vertical plane. Obviously, this may be varied 115 as found desirable.

While the belt arrangement of Fig. 33 provides what may be considered as a traveling table or carrier for receiving the labels, the co-operation therewith of belts d and d' serves to more or less grip the label adjacent 120 its ends, so that upon further travel of the belt structures, belt a^2 may pass out of the table-forming relation without affecting the position of the label on the remainder of the table, the general belt arrangement, at this 125 time, being shown in Fig. 36, in which the label is shown as having the central portion of its under side exposed and carrying adhesive coating.

The container is brought into engagement 130

with this exposed adhesive-coated face of the label.

In order to provide the necessary rapidity of feed of the containers to provide the high capacity of the machine, the containers are preferably fed in a plurality of rows or travel paths, the machine of the drawings employing two of such rows, the containers being supplied from a suitable source and 10 successively delivered to a container feeding or transfer drum which co-operates with both container runways so as to receive the containers therefrom successively, the drum being arranged in such manner as to deliver 15 the containers so received to an endless container carrier, the drum being so arranged that successive containers are delivered from different runways. The containers, in the embodiment shown, are delivered to the carrier with the container axis extending practically horizontally, thus placing a portion of the curved face of the container as the outermost portion of the container when in position.

25 The container carrier has a path of travel such as will cause such outer face of the container to pass into contact with the exposed adhesive coated portion of the label, the carrier being arranged to travel upwardly in 30 an inclined direction relative to the horizontal plane in which the label is traveling. As the container carrier and the belt structures are traveling at synchronous speeds, and are so timed that when the container face 35 reaches the plane of the label, the two elements—the container and label—are relatively positioned to locate the label at its proper point on the container. As both elements continue their advance movements, 40 the gradual upward movement of the container, through the travel of its carrier, raises the label at its central portion, as indicated in Fig. 37, the ends of the label being thereby withdrawn from the gripping belts 45 during this advancing movement.

When complete contact between label and container is had, the upper face of the label is brought into contact with a holding or gripping structure which acts to grip the 50 positioned portion of the label on to the container, the gripping device being arranged to travel in its gripping position during such upward travel of the container carrier, thus holding the label in position through 55 succeeding operations, the gripping contact being maintained for sufficient length of time to insure that the label will not be moved out of position during the succeeding operations. The withdrawal of the label 60 ends is with sufficient freedom to prevent tearing of the label, it being understood that no material resistance is present on the adhesive side of the label, so that the resistance against such withdrawal is mainly provided by belts d and d' , this resistance being suffi- 65

cient to insure that the label is caused to firmly engage the face of the container.

As the container carrier continues its movement, this withdrawal action will continue until the entire label has been removed 70 from the belt structure, the position shown in Fig. 38, in which the label is shown as in embracing contact with approximately half the container circumference, the free ends of the label projecting downwardly. This 75 carries the container above the plane of the belts which are then led past cleaning structures for removing surplus adhesive, leaving their surfaces clear for the application of a new coating.

80 Further travel of the container carrier brings the container into the sphere of action of a pair of rotating wiper brushes which are arranged to gradually wipe additional portions of the label on to the 85 periphery of the container—increase the length of label contact with the container—Figs. 39 and 40 indicating two of the different positions which may be occupied by the container during its travel through the 90 zone of activity of these brushes.

95 The container and label are practically in the relation shown in Fig. 41 upon reaching the end of the brush activity, and further movement of the carrier is arranged in such manner that the container is automatically released from the carrier, the container being transferred on to a rotating transfer device, the transfer being in such manner that the container is reversed in position, viz: the downwardly projecting ends of the label provided while on the carrier are caused to project upwardly.

100 Movement of the transfer device successively delivers the containers on to a runway 105 along which the containers, with the projecting ends upward, are caused to move and pass into the zone of activity of a pair of wiping brushes which wipe the remaining 110 unaffixed portions of the label on to the periphery of the container, thus completing the labeling operation.

115 During the operations forming these cycles, both label and container are continuously advanced—carrier movements being continuous and the movements during final wiping being substantially continuous—so that practically no delay in presenting successive labels and containers is had by the presence of the preceding label or 120 container, this length of time being reduced to a minimum through the fact that the advancing movement is in a direction which corresponds to the width or narrowest portion of the container and label. Consequently, capacity of the machine is limited 125 only by the ability to present the containers and labels. Although the labels and containers are delivered to the several carriers in rapid succession, a sufficient length of 130

time to complete the labeling cycle is given, so that assurance is had that each label will be properly applied, the capacity being provided by the ability of each of the mechanisms to accommodate for operation on containers in rapid succession, an arrangement by which a continuous advancing movement is had, enabling these mechanisms to accommodate for a comparatively large number of containers undergoing labeling activity concurrently.

In describing the specific embodiment disclosed herein, the respective mechanisms will be referred to in the general order above outlined.

The several mechanisms are mounted on a suitable frame structure indicated generally at 60, the specific form of the frame structure which may be employed being obviously a matter of structural detail, variable as desired. Obviously, the frame may be an integral structure or formed of a plurality of members as may be most convenient, the essential being that those members which carry parts adapted to be operated in synchronism shall be properly positioned in order to insure that the synchronous movements be had and maintained.

30 *Label feeding mechanism.*

This mechanism comprises a label supply drum structure A and a label segregating and feeding structure B—which may be termed a picker—these structures being in the form of drums geared together to rotate in opposite direction, these drums being driven from a suitable drive shaft 61 mounted in the frame and driven from a suitable source of power, as for instance, 40 a motor, not shown. Shaft 61 carries a gear 62 which is adapted to drive the drum of structure A, as by engaging gear 62 with a gear 63 of drum 64 of structure A, gear 63 being adapted to mesh with gear 65 of drum 45 66 of structure B.

Referring more particularly to Figs. 7 to 12 inclusive, drum 64 is shown as formed of a stationary side member 67 mounted on the frame (Fig. 3) and a member 68 mounted on shaft 69, member 68 rotating with shaft 69, gear 63 being shown as secured to member 68.

Secured to member 68 is an annular plate 70, preferably of wood, this plate being located without a cylindrical member 71 concentric with shaft 69, said member 71 forming the bottom of a plurality of pockets or compartments which have their opposite ends closed by plate 70 and the inner face 55 of member 67 respectively, the sides of the pockets being provided by partitions 72, these partitions being arranged in parallel pairs to produce pockets which have their directions of depth in correspondence with 60 radii of the drum. The open outer ends of 65

the pockets are more or less restricted by a plurality of plates 73 (Figs. 9 and 10) having spaced lips 73^a which project slightly over the open ends of the pocket. These plates may be removably secured in position to permit of the introduction of the labels into the pockets, each pocket being designed to receive a plurality of labels.

In each pocket is a follower 74 (Figs. 11 and 12) preferably non-circular in cross section and having one end provided with a suitable washer 74^b. The body portion of the follower is of less length than the length of the pockets, and carries an extension 74^b which is yieldingly supported by the body portion, as by spring 74^c, the extension carrying a washer 74^d of suitable material. Relative movement of the extension and body portions is limited by suitable means as for instance, a pin and slot structure 74^e. The followers are located at the bottom of the several pockets, and the general arrangement of the follower is such that the weight of the follower will tend to retain the labels in compact arrangement and with the outer 90 label in contact with lips 73^a, a frictional contact of the ends of the follower with the end walls of the pockets permitting this action to take place, while at the same time preventing a follower floating action as the 95 drum rotates.

As will be obvious, any desired number of pockets may be employed, the particular embodiment shown in the drawings employing forty pockets. Since each pocket has a 100 depth sufficient to contain a pack having a large number of labels, it will be understood that the drum, when loaded, will carry a supply of labels sufficient to permit of operation for a considerable length of time even 105 under the high capacity of the machine.

Obviously, the pockets may be otherwise exposed for the insertion of labels, as by arranging for the ready removal of member 67, or the parts may be arranged to permit member 68 to be moved longitudinally of shaft 69, these being various ways in which the pockets may be exposed.

The outer labels are removed from successive pockets during rotation of drums 115 64 by the action of operating mechanism carried by drum 66, the latter being mounted on shaft 75, gear 65 being carried by member 76 of the drum. Secured to member 76 is a cylindrical member 77 arranged concentric with shaft 75 and which is provided with a plurality of rows of openings, each row extending in the direction of the axis of the drum. The number of rows of openings corresponds to the number of pockets 125 of drum 64, and member 77 may be provided with a projecting portion 77^a through which the openings extend radially of the drum. Drums 64 and 66 are so mounted and geared together that during the drum revo- 130

lutions a projection 77^a is brought into direct opposition to the open end of a pocket, the outer faces of the projections practically contacting with plates 73 bounding the open ends of a pocket, thus tending to produce a close connection between the two drums at the particular point where such contact is had.

78 indicates a plurality of pipes located inside of member 77 and extending in the direction of the drum axis, each pipe serving as a header for a plurality of short pipes 78^a which project through the openings in member 77, the head 78 being located in radial alignment with the rows of openings, the number of headers preferably being equal to the number of rows. Each header is connected with a rotatable member 79 by pipe connection 78^b, the inner ends of the connections 78^b extending radially from member 79, as shown more particularly in Figs. 13 to 16 and Fig. 19. The inner ends of each connection 78^b are in open communication with a laterally extending port 79^a leading to the inner face of member 79, as more particularly shown in Fig. 19. This general arrangement brings the open ends of the pipes 78^a of a row in direct open communication with a port 79^a individual to the row of pipes. By bringing any one or more of the ports 79^a into communication with suction-creating mechanism and practically preventing entrance of air into the outer ends of pipes 78^a, the suction is made effective at the outer ends of such pipes. In the present structure, this action is produced at the instant when one of the projections 77^a is in contact with the opposing walls of the open end of a pocket, thus making the suction effect active to withdraw the outermost label of the pocket from beneath the lips 73^a and into facial contact with the face of the projection, thus practically sealing the open ends of pipes 78^a by the action of the suction, this sealing action being maintained until the suction is broken by admitting air into the suction line.

Since it is desirable that these individual suction lines be maintained only during that portion of travel of the drum through which the label is to be carried, controlling mechanism is employed for connecting up those individual suction lines to the suction mechanism at the proper time and for the proper length of time. This controlling mechanism is shown more particularly in Figs. 13 to 19 inclusive, in which 80 indicates a member loosely mounted on shaft 75 and which has its inner face in contact with the inner face of member 79, being held in such contact by a pressure applying member 81 carried by and rotatable with the shaft and between which and the outer face of member 80 a suitable retaining mechanism is made active, a simple

structure being that of a leather ring 81^a in contact with member 80, a steel ring 81^b between a flange of member 81 and said leather member, said flange 81^c carrying bolts 81^d which are adapted to place pressure on the steel member 81^b, thus causing the leather member 81^a to firmly contact the outer face of member 80. While more or less pressure is thus provided, it will be readily understood that slippage may occur between the several members so that if member 80 is held from rotation, the shaft and the parts carried thereby may readily rotate and yet provide an efficient surface contact between members 79 and 80. Obviously, other forms of mechanism may be employed for the purpose or other materials may be used.

Member 80, which may be termed a valve member, is provided with a segmental channel 80^a extending to its inner face, and the advance end of this channel is connected to a suitable suction-creating mechanism, not shown, by a pipe connection 82 (Fig. 3) preferably partly flexible and partly rigid. Mounted in channel 80^a is a member 83, shown more particularly in Figs. 17 and 18 said member being curved in its direction of length and having a laterally projecting pin or arm 83^a, said pin or arm projecting outwardly through a segmental slot 80^b to the outer face of member 80, said pin or arm being connected to a suitable bracket carried by the frame and which is adapted to hold member 83 against movement. Member 83, which may be termed a key or valve, is of a length less than the length of segmental channel 80^a and serves to close the open ends of those ports 79^a which may be opposite this member. Obviously, if valve member 80 be rotated to increase or decrease the length of the advance end of channel 80^a, the number of ports 79^a which may be in active communication with the suction-creating mechanism may be readily varied. This variation is shown by comparing Figs. 15 and 16, in which Fig. 16 has member 80 in the position shown in Fig. 13, pin or arm 83^a being located at one end of slot 80^b; Fig. 15 shows member 80 moved to a position where the pin or arm is at the opposite end of this slot. These two positions of member 80 represent the position when the machine is not in operation (Fig. 15) and the running position (Fig. 16).

As shown in Fig. 15, the range of movement of member 80 is such that the key or valve does not reach entirely to the advance end of slot 80^a, a stop pin 80^c coöperating with a suitable stationary structure of the machine preventing sufficient movement of member 80 to cause the valve to reach the end of the slot. Consequently, one of the ports 79^a (that port which has the outer end of its suction line in label withdrawing posi-

tion) is in position to have suction activity. In this position of the valve the remaining ports are closed from such activity through the presence of the key or valve opposite 5 such ports.

In order to provide the feeding or label delivery action involved in carrying the label through the desired length of travel of drum 66, member 80 is shifted to the 10 position shown in Fig. 13 which has the effect of increasing the length of the advance end of the channel open to suction action and uncovers a plurality of ports 79^a. A stop pin 80^a limits the advance movement of 15 member 80.

As will be understood, opening of an increased number of ports 79^a to the suction chamber provided by channel 80^a renders a corresponding number of suction lines active. 20 Should this communication be established without closing the outer ends of the lines, the suction effect would be practically lost. To avoid this difficulty, I prefer to employ the particular form of retaining device 25 described, which tends to produce a frictional effect between flange 81^a and member 80. This enables shifting of member 80 from the position of Fig. 15 to that of Fig. 16 to take place automatically by 30 the rotation of shaft 75 during the operation of the machine, the successive ports 79^a becoming active only as the outer ends of their lines are in proper relation with the proper pocket of drum 64. As before pointed out, one suction line is active whenever member 80 is in the position of Fig. 15, and as each port opens, its outer end becomes closed by a label from the label supply. When the advance travel brings pin 80^a into 40 contact with its co-operating element, the desired number of ports will then have been opened, and each of the suction lines thus produced will have their outer ends closed by individual labels. In Fig. 16, nine ports 45 are shown as active.

While member 80 is thus held stationary in the position of Fig. 16, member 79 is continuously rotatable in the direction of the arrow in Fig. 16, so that the ports 79^a will 50 successively pass into suction communication at the rear end of the open portion of the channel, while those ports at the advance end will successively pass out of suction communication. This breaking of suction communication, however, does not immediately release the labels owing to the fact that members 79 and 80 are in contacting relation, so that a more or less holding effect is retained on the labels until the perforation 55 reaches a cut-out portion 80^a of member 80, this cut-out portion being open to the atmosphere, and hence permits the suction line to be flushed with air, the result being that the label is free to drop or be released 60 from its held position, the release being

aided by the in-rush of air through the connections. This cut-away portion may, therefore, be considered as a label-releasing element. Obviously, the suction lines, after being flushed in this manner, remain inactive until again rendered active by having their ports brought into communication with the suction chamber.

The release element (the cut-away portion 70 80^a) is active on the ports successively. Hence, by providing means for receiving each label as it is released, and moving the receiving element at a speed sufficient to carry the released label out of the way of the label next to be released, with the support traveling at a uniform speed, preferably a speed synchronous with the surface speed of drum 66, it will be readily understood that labels can be positioned on the support in rapid succession and uniformly 80 spaced on the support.

Label feeding and adhesive-applying mechanism.

As heretofore pointed out, the support on 90 which the labels are thus received is in the form of a plurality of belts (diagrammatically indicated in Fig. 33), these belts serving not only to feed the blank in its advancing direction, but also to apply adhesive 95 thereto during such advance movement. The particular mechanism employed in the present embodiment will now be described.

Referring more particularly to Figs. 1, 1^a, 2 and 2^a, 84 indicates a band-carrying member having a circular contour and mounted on shaft 85, said shaft being driven through suitable gear connections with drive shaft 61. Mounted at the opposite end of the machine is a similar member 86 mounted on shaft 87, shafts 85 and 87 being connected to rotate in unison through a suitable drive connection indicated by the dotted line 88, thus causing members 85 and 87 to rotate in unison. These members carry endless bands 100 a, and a', the upper flight of these bands passing beneath drum 66 and over a table structure 89, the direction of movement being indicated by the arrow in Fig. 2. At a suitable point and preferably in proximity 110 to the point where the belts enter their upper flight, I provide a suitable adhesive applying device indicated at C. This device is of any preferred arrangement, shown as in the form of a roll or rolls dipping into 120 a supply tank and contacting with the outer face of the bands or belts during the band travel, the structure being adapted to coat the outer surface of bands a and a' as well as the similar surface of band a^a which is 125 brought into proper relation to bands a and a' in advance of this adhesive-applying point. Consequently, the outer surface (the upper surfaces of the upper flight) of the bands are provided with an adhesive coat- 130

ing when reaching the point where the labels are successively released, the result being that each label is deposited at a particular point on the belt and in contact with the 5 coated surfaces of these belts.

During the movement of bands a and a' in their return flight, they are passed through suitable cleaning devices, indicated generally at D, and which are adapted to remove 10 the unused adhesive from the surfaces of the bands, thus cleaning the bands before again subjecting them to the adhesive-applying action. The cleaning devices may be of any suitable type, as for instance, a rotating 15 brush structure movable relative to the band, the brush being adapted to be kept clean by dipping into a tank of water. Obviously, other forms of cleaning mechanism may be employed. If found necessary and 20 desirable, suitable belt-tightening devices may also be placed in this return flight.

The adhesive-applying mechanism may be operated in any desired manner, the applying rolls being operated either by frictional 25 contact or by a direct drive mechanism, each type being well-known in the art.

While belts or bands a and a' are carried by both members 84 and 86, band a^2 , also of endless form, does not extend to member 86, 30 this band passing over member 84 and beneath drum 66 (thus producing the three band arrangement of Figs. 33 and 34), and then passing out of such position as it is carried over a roll 90 which acts to produce 35 the upper end of a downward flight, the band then returning to member 84, such returning movement preferably causing the belt to pass through a surface cleaning device D of suitable form. This shifting 40 of the direction of travel of band a^2 leaves bands a and a' as the remaining supporting band flight. In advance of the point where band a^2 leaves its label supporting position, bands d and d' are brought into activity 45 these bands having a lower flight parallel to the upper flight of bands a and a' . Bands d and d' are supported at the opposite ends 50 of such lower flight by rolls 91 (Fig. 2^a) and 92 (Fig. 2), these rolls being suitably supported, roll 92 being shown as mounted 55 on a swinging bracket 93 preferably weighted. If desired, roll 91 may be similarly mounted. After passing roll 91, bands d and d' pass upwardly around suitable 60 rolls and preferably through a cleaning mechanism D', of suitable type, and then forwardly to roll 92, the latter roll being preferably mounted over table 89. If desired, suitable belt-tightening mechanism 94 may 65 be provided.

As will be understood, the weight action of roll 92 tends to press the labels into close contact with the adhesive coating of belts a and a' as these belts carry the successive 70 labels beneath said roll, thereby insuring a

proper application of the adhesive to the labels. As this roll is at the entrance to the particular band relation shown in Fig. 35, the label will practically be gripped by the opposing bands after band a^2 passes out 75 of its supporting position, as indicated in Fig. 36, the gripping band relation being maintained until the several bands reach the end of the label engaging flights and enter their return flights.

While the several operations on the labels thus described are such as to accurately position the labels at regular successive intervals on the traveling band structure, it is obvious that such positioning is more or 80 less dependent upon the proper action of drum 66 in transferring the labels from receiving to releasing positions. Owing to the particular relation of parts, this feed will be accurate as long as the suction action 85 is maintained. This, however, depends upon the presence of a complete label at the outer ends of the suction line. Should the label received from drum 64 be of a size which would expose one or more of the open ends 90 of pipes 78 or should a partial tear of the label expose either of such open ends, the suction action would be more or less ineffective, owing to the more or less bleed action at such entrance end.

As it is preferred not to employ labels of this type in the operation, suitable mechanism is employed for meeting this condition by automatically carrying the belt flights away from normal proximity to drum 66, it 100 being understood, that during normal operation such drum practically places the label in contact with the supporting bands. By carrying the bands away from such normal position, the face of drum 66 will not become 105 coated with the adhesive through contact with the belts when labels are missing, a feature of importance in view of the fact that these label-supporting faces of drum 66 must be free from any coating which would 110 tend to prevent the labels from being properly released during normal operation.

Any suitable form of shifting mechanism may be employed, one form suitable for the purpose being shown in Figs. 20 to 24 inclusive in which such shifting of the bands is not only taken care of automatically, but is also rendered effective when the machine is 115 inactive or when member 80 is shifted to the position shown in Fig. 15.

95 designates a lever (Fig. 20) pivoted to a stationary portion of the frame and extending beneath and transversely of the upper flight of bands a , a' and a^2 . Said lever is connected to a vertically movable 120 frame 96 guided on pins 96^a, a suitable connection 97 extending between the frame and lever. Frame 96 carries a plurality of shoes 98 which are positioned beneath the belts or bands. Said frame also carries a roll 99 130

positioned above and extending transversely of the bands, shoes 98 being positioned in proximity to the point where the bands receive the labels from drum 66. The shoes 5 and roll are relatively positioned so that during normal operation of the machine, roll 99 is out of contact with the bands while the shoes are in contact with and are adapted to position the bands practically in contact 10 with the labels carried by the drum, springs 100 aiding in supporting the frame in this position.

The surface speeds of drum 66 and of the band-formed label support are preferably 15 equal so that the label is moved in contact with the support without liability of damaging the label or shifting its position on the support, the particular projection 77^a which may be in contact with the support 20 simply moving through its arc of travel in contact with the support, the release of the label taking place during this travel through the arc, springs 100 permitting sufficient yielding to accommodate 25 date for the label. When, however, no proper label is present to protect the face of the projection 77^a from the adhesive coated face of the bands, either through the presence of an improper label or when it is desired 30 to stop the machine, roll 99 is brought into contact with the bands and moved downwardly so as to carry the face of the bands away from contact with drum 66, this movement of the roll being provided by moving frame 96 downwardly.

The movements of frame 96 are made dependent upon variations in opposing pressures made active on lever 95, said lever having its free end provided with a bracket 101 40 to which is secured a cylinder 102, bracket 101 carrying a structure adapted to close the lower end of the cylinder. Said bracket also carries a yoke structure 103 to which is secured a suitable weight 104.

45 105 indicates a stationary tubular member, the lower end of which carries a piston structure 106 co-operating with cylinder 102 to form a chamber 107 between the end of the piston and the closed end 101^c of the cylinder. The opposite end of member 105 leads, through a valve structure 108 to the line connections of the suction-creating mechanism, as for instance tube 82.

55 Valve structure 108 as shown more particularly in Figs. 23 and 24, in which a casing 108^a carries a plug 108^b movable endwise, said plug having a channel or port 108^c, which, in one position (Fig. 23) provides open communication between suction 60 line 82 and member 105, thus bringing the suction line into direct communication with chamber 107 with the result that cylinder 102 is moved upwardly in opposition to weight 104, bringing the shoes into operation, it being understood, that the suction

pressure produced in chamber 107 under normal operating conditions is in excess of the weight pressure, this excess being present as long as the suction pressure is maintained within chamber 107. As heretofore 70 pointed out, the normal operation with proper labels practically prevents feeding of air to the suction lines and hence this suction pressure is maintained. Should, however, drum 66 fail to pick a label from drum 75 64 as when the pocket supply is exhausted, or proper closing of pipes 78^a be prevented through the presence of an improper label, or because of other difficulties which would prevent the label closing the outer ends of 80 the suction line when suction is made effective in drum 66, feeding of air at such point affects the suction in the various lines to such an extent as to bring the suction pressure in chamber 107 below the pressure of 85 weight 104, the result being that lever 95 is moved downward under the excess pressure and, through the connections, renders roll 99 active to withdraw the bands from 90 out of contact with drum 66.

95 As will be understood, this feeding of air will be made effective practically at the row of pipes 78^a which is just leaving the label picking or segregating position, and as such row is required to travel a distance in 95 reaching the point where the label is to be delivered to the band-formed support, sufficient time will be given to permit the lever to become active and shift the bands. If desired, the movement of lever 95 can be 100 employed for controlling the stoppage of the machine; various well-known mechanisms made operative by movements of this character may be employed for this purpose. As will be understood, connection between chamber 107 and suction line 82 is 105 dependent upon positioning of port 108^c at the proper point. As plug 108^a is supported by a spring 108^b which tends to move the plug in a direction to carry port 108^c 110 out of such position, means are provided in the form of an arm 109 and a stem 108^e for moving the plug to the position shown in Fig. 23 and maintaining it in such position, arm 109 being carried by a part which is 115 movable with member 80, as for instance, a rigid portion of suction line 82. When member 80 is moved to the position shown in Fig. 15, the movement carries arm 109 away from its holding down position, permitting spring 108^b to shift the plug and thus break the continuity of the suction line through port 108^c, the position being shown in Fig. 24. To permit feeding of air to chamber 107 when the plug is moved to this 120 position, casing 108^a is provided with a bleed opening 108^d and plug 108^b is provided with a port 108^e which is brought into connection with member 105 when the plug is in this position. Consequently, air 130

will enter through opening 108^c and feed chamber 107, thus affecting the suction pressure in such chamber and permit weight 104 to shift lever 95.

5 *Container feeding mechanism.*

As heretofore pointed out, the labels and containers are continuously fed from their respective sources of supply and are brought 10 into positions where the label affixing action begins, the latter operation taking place while both are traveling. The feeding of 15 the labels to such position and the mechanism for providing such feed are above described. I will now describe a mechanism for placing the containers in position to co-operate with the labels.

As heretofore pointed out, the apparatus, when arranged for large capacity operations, 20 preferably employs a container feeding mechanism which receives its supply from a plurality of sources. In the disclosed embodiment I have shown the use of two runways each of which is adapted to 25 deliver the containers to the feeding or container-delivery mechanism within which the containers are manipulated to discharge them from the feeding mechanism in a single succession. This enables supply of 30 containers to the applying mechanism in sufficiently rapid succession to enable a large capacity to be obtained.

A general form of mechanism for delivering the containers to the feed mechanism is 35 shown in Figs. 2, 3 and 5, being of a form adapted for the delivery of cylindrical containers having flat top and bottom surfaces, a type of container employed for many purposes, being more or less shallow and provided with a removable top, which, before 40 the container is brought to the machine, is in closed position with the container filled, the containers of this type having the label secured to both lid and body. However, 45 the machine is adapted to operate with unfilled containers, and the invention is, therefore, not limited in this respect.

As the two runways are substantial duplicates, a specific description of but one of 50 them is given.

110 designates a suitable frame composed of bars and rods arranged to form a runway with rods or bars 110^a forming the sides of the runway, the container moving 55 through the runway with its cylindrical walls opposing these side bars. As shown in Fig. 3, the runway is preferably arranged with a portion extending approximately horizontal and is then changed to a more or 60 less vertical direction with the discharge end preferably curved toward the feed mechanism. The horizontally-extending portion is preferably slightly inclined downwardly in the direction of advancing movement, and 65 this portion preferably employs an endless

conveyer band structure with its upper flight practically forming the bottom of the runway, the conveyer, indicated at 111, being driven from a suitable source and is effective not only to support the containers but 70 also as a means for bringing successive containers into contact and maintaining them in such contact while within the runway, it being understood, of course, that relative movement between the band or belt and the 75 container is possible. This tends to insure a constant supply of containers at the discharge end of the runway even though the positioning of containers at the entrance end of the runway may vary as to timing, 80 etc. The positioned containers then pass downwardly through the approximately vertical portion of the runway to the discharge end, the latter being provided with a suitable gate mechanism, indicated generally at 112, which permits of the release of the containers singly. In the form of structure shown, the rotating feed mechanism operates to open the gate for the passage of a container after which the gate closes until 90 again opened to discharge the next container. The particular structure shown is of a well-known type and is not further described inasmuch as any one of a number of types of structure may be employed for 95 the purpose.

It will be understood, of course, that each of the runways is intended to maintain a constant supply of containers which are adapted to be released one by one from the 100 runways. It may be noted at this point that in operation, the gate structures for these runways operate alternately to discharge containers first from one runway and then the other.

The container feed mechanism, shown in 105 detail in Figs. 25 to 30 is in the form of a built-up drum structure which is adapted to receive the individual containers alternately from the runways and discharge them 110 successively on to a container-carrier presently more fully described.

113 indicates a shaft suitably supported on the frame and on which is a suitable wheel 114,—a sprocket wheel may be employed—on which the container-carrier is mounted, the latter being driven as presently described, the resultant movement of sprocket wheel 114 serving to rotate shaft 113. Mounted on shaft 113, on opposite 115 sides of the sprocket wheel are built-up structures, rotatable with the shaft, and which are adapted to receive the containers individually and deliver them to the carrier while the latter is passing around the 120 sprocket wheel. The built-up structures are 125 duplicates in principle but are structurally reversed, and a description of but one of these structures is, therefore, given.

Referring to Fig. 25, 115 indicates an 130

outer disk, 116 an intermediate disk and 117 an inner disk, these disks being spaced apart to receive blocks which are adapted to form compartments and runways for the transfer of containers through the feed mechanism, these blocks also forming spacing members for the disks.

As shown in Figs. 26 and 27 the space between disks 115 and 116 contains a plurality of blocks 118 spaced equidistant therein, these blocks being shown more particularly in Fig. 30, sections of the blocks being shown in Figs. 26 and 27. As shown, these blocks have a face 118^a carrying a guide 119 inclined to the direction of length of the face. The blocks are of a more or less triangular configuration, with a portion cut away, as at 118^b, said blocks also having another face 118^c. These blocks are positioned in such manner that face 118^a of one block opposes face 118^c of an adjacent block with guide 119 positioned therebetween. A third face 118^a completes the triangular shape of the blocks.

As will be seen, face 118^a extends to the periphery of the disks and is adapted to form a seat for the container when it enters the feeding mechanism, this point being indicated by the arrow *x* in Fig. 26, arrow *y* indicating the direction of movement of the parts. As shown in this view, the outer portion of the face forms the bottom of a pocket-like space open for a considerable distance in the direction of travel of the structure. Hence, the delivery of the containers into this space can be varied as to time, thus insuring each space will receive a container as the spaces are successively brought opposite the discharge end of a runway.

When the container is received, it rests with one of its flat faces on such seat. Hence, at the time of container introduction, its movement on the seat will be comparatively slow, owing to the slight inclination of the seat at time of container introduction. As the device rotates, the container slides toward the axis of the device; its movement increases in velocity due to increase in angularity of face 118^a relative to a horizontal plane. This movement of the container brings it into contact with the outer face of guide 119 which is inclined inwardly toward the device axis in the direction of disk 116. Disk 116 carries openings 116^a (Fig. 27) in alignment with guides 119, so that when the inward movement of the container brings its cylindrical face into contact with a guide, the container will roll toward and through opening 116^a into a compartment formed between disks 116 and 117, thus removing the container from a position between disks 115 and 116 to a position between disks 116 and 117, and at the same time bringing the container to a point closer to the axis of the device, these movements being through gravity,

the transfer taking place while the container is at or approaching the top of the device.

The space between disks 116 and 117 contains a plurality of blocks 120 of general wedge shape and spaced apart to form channels 120^a. Each of these channels is provided with a pair of guides 120^b and 120^c, these guides having faces inclined to the horizontal approximately as shown in Fig. 25, guide 120^c practically forming a continuation of guide 119, so that when the container rolls through opening 116^a it continues this movement on guide 120^c until it contacts with inner disk 117, this movement taking place while the container is at the top of the device. As the device continues its travel, the particular channel in which the container is located passes a horizontal plane, the outer end thus passing below the inner end of the channel causing the container to begin a sliding movement outward through the channel toward the outer guide 120^b with which it contacts and is brought into alignment with an opening 117^a in disk 117, this opening extending to the outer periphery of the disk. As guide 120^b is inclined in a direction to cause the container to roll through opening 117^a, the container is in position to pass through such opening, this position being reached in advance of the time when the channel reaches a vertical position. To prevent the container from passing out of the channel in advance of the proper point in the travel of the device, a plate 121 is provided, this plate being secured to a stationary portion of the frame and extending downwardly in proximity to the inner face of disk 117. As shown in Fig. 29 this plate is provided with a cut-out portion, this cut-out portion being located at such a point that when the container reaches and passes the advance wall of such portion, the restraint against movement of the container through opening 117^a is removed. As the container is positioned on the inclined guide 120^b at this time, it is obvious that when this restraint is removed the container will roll out through the opening into the space between the opposing plates 121. This movement takes place while one of the carrier links is in position opposite the opening, so that the container is automatically delivered in position to be picked up by the container-carrier.

As will be clear, all movements of the container within the device are provided by gravity and the arrangement is such that these movements begin gradually so that there is no liability of the container being materially agitated while within this transfer mechanism, an important consideration where the contents are of a type which might sift from the container under such agitating conditions.

As before pointed out, the feed devices are substantial duplicates but oppositely arranged. They are also offset with relation to each other, so that one device becomes active during the time when the other device is bringing its succeeding face 118^a into position to receive the container. Consequently, the discharge of containers on to supports 122 is successively from different devices, so that while each device may be able to receive and transfer a certain quantity of containers during a predetermined period, the actual delivery of devices into the path of travel of the container carrier is substantially double such quantity during the same period of time.

The particular form of feed mechanism thus shown and described is one form in which a feed mechanism for the purpose may be provided. Obviously, other forms of delivery mechanism may be used, and it is to be understood that the invention is not specifically limited to this particular embodiment, excepting in so far as it may be specifically claimed. Where the machine is designed to operate at a sufficiently low capacity, or where the containers are of a type which will permit of rapid positioning movements, a single feed mechanism may be employed in which the containers are delivered directly to the carrier, feeding mechanisms of this type being well-known in the art. The present embodiment is designed more particularly to meet the condition of a relatively large capacity with containers carrying contents which may sift therefrom under agitating movements or the containers be damaged by such movements, and at the same time, provide a compact arrangement it being understood that by the lateral transfer of containers the supply can be brought to the device without affecting the label carrier structure and arrangement.

The container feeding structure is located below the plane of the upper flight of bands *a* and *a'* and located beyond the point where band *a*² leaves such flight, so that at the time when the advancing travel of the label brings it to the location of the container feeder, the condition indicated in Fig. 36 is present, the under face of the central portion of the label being coated with adhesive with such coated face entirely exposed. While the label is traveling in this condition, the upper curved surface of the container is brought into the path of travel and the beginning of the label-affixing cycle takes place. For the purpose of describing this particular cycle, I will indicate the mechanism as the

Label affixing mechanism.

During the major portion of the label-affixing operation, the containers are positioned on an endless traveling carrier or

conveyer formed of a link construction, which, as heretofore pointed out, extends over sprocket wheel 114 of the feeding mechanism, 123 indicates a sprocket wheel mounted on shaft 124 positioned above the plane 70 of the label travel path, the carrier or conveyer being mounted on sprocket wheel 123. The relative positions of sprocket wheels 114 and 123 is such that the upper flight of the carrier extends upwardly in an inclined 75 direction and passes through the plane of the path of travel of the advancing label and between bands *a* and *a'*.

The carrier or conveyer is formed of a plurality of links which include link structures of the type indicated in Fig. 31, in which 125 indicates a pair of arms extending outwardly from connecting sections of the chain, these arms or plates being spaced apart and adapted to receive a block 125^a 80 having a foot 125^b and to which is secured what may be termed a button 125^c, the arrangement being such that arms 125 are more or less inclined to the general direction of the links, so that during the period when 90 the conveyer is traveling in its upwardly inclined direction—the upper flight of the conveyer—arms 125 extend upwardly in a vertical plane, as shown for instance, in Fig. 6. The space between adjacent link structures is adapted to receive a container, the latter, during the upward flight, resting on foot 125^b. As the spacing between the rear of one link structure and the front face of the button of the succeeding structure is 100 preferably substantially equal to the overall depth of the container, it will be understood that during the period of time the container is being carried through this flight, it is practically gripped between adjacent 105 link structures and held against movement, these structures thus supporting and gripping the container at this time. For purposes of description I have termed these link structures as link supports, and while I prefer to employ a structure of the type indicated, it is obvious that other types may be employed and the invention is not to be considered as limited to this particular form of support.

Obviously, the space between the outer ends of adjacent link supports will increase where the conveyer passes about the periphery of either of the sprocket wheels, and the relative arrangement is preferably such that 120 such increase in spacing takes place at such time as will have a more or less increase when the containers are introduced into the path of travel of the link supports, as shown, for instance, in Fig. 5. As indicated in Fig. 121 125, the link supports travel above and intermediate the plane of supports 122, the latter being curved and extending a suitable distance above a horizontal plane intersecting the axis of the container-feeding mechanism. 130

When, therefore, a feeding device brings a container to the position where it is free to roll out through its opening 117^a in a direction transverse to the travel of the conveyer, it passes into the space between successive link structures and is freely movable on supports 122, as shown in Fig. 25. This places the container in the path of travel of the rear link structure. The advancing movement of this link structure carries the container upward in contact with supports 122 until the link structure passes a horizontal plane intersecting the axis of the feeding mechanism, whereupon the container will gravitate inwardly away from supports 122 and toward foot 125^b with which it contacts and which stops the inward travel of the container. This takes place in advance of the time when the conveyer leaves sprocket wheel 114, so that as the conveyer straightens out in entering the inclined flight, the container clamping action is provided between the adjacent link structures. In this way, each container is accurately positioned in the conveyer without any material agitating action and serves to prevent any possibility of the container top passing out of position.

As will be understood, the spacing may be such as to dispense with this clamping action, and I reserve the right to modify the arrangement in this respect. However, this clamping is preferable, and where a materially different depth of container is being operated upon, buttons of a different thickness can be substituted if desired.

It should be noted that this particular arrangement positions the container with its axis substantially horizontal, so that the upper face of the container extends in approximately the same direction. The conveyer and the label supporting band structure travel at synchronous speeds, and the label feed structure operates in synchronism with the band travel in such manner that a positioned label reaches the point where the upper surface of the container intersects the label traveling path at the instant that the two elements—the label and container—are properly related to each other as to label registration and position on the container. Due to the manner in which the container approaches the label, no relative slippage will occur and hence, the only label movement is that provided by the action of the container on the label.

The synchronous movement of the band-form label support and the conveyer is provided by operatively connecting shaft 124 with shaft 87, suitable gears or chains being provided for the purpose, the drawings showing a gear connection. Since shaft 87 is driven from shaft 85, it will be readily understood that the several parts are connected to move in synchronism, any differ-

ence in speed being determined by the form of the connections, the drive, however, being positive throughout.

As heretofore pointed out, the container feeding structure is carried by shaft 113, this latter shaft being driven by the conveyer, so that assurance is had that successive containers will each be delivered at the proper instant. Through these various drive connections, which are properly timed to produce the result, it will be readily understood that when the traveling container is brought into contact with the traveling label, proper registration of the two elements will result so that as each container reaches this point it will find its label properly positioned within the label band-formed carrier.

After the container is brought into contact with the label, the further advancing travel of both causes the container to exert an upward pressure on the exposed portion of the label, the container gradually moving upwardly through the space between bands *a* and *a'*. Such upward movement tends to withdraw the ends of the label from between the opposing belts or bands, the latter tending to provide a slight resistance to such withdrawal action so that the label is drawn into close contact with such portion of the container, the end-withdrawing action continuing as the advancing movement continues until the label has been entirely withdrawn from between the belts through the upward travel of the container.

While the container is preferably clamped in position during the upward travel, as heretofore explained, such clamping action is, of course, not effective on the label, and since further applying action is to take place—the end-withdrawing action leaving the ends of the label as in Fig. 38—I prefer to employ an additional holding means which acts to clamp the label in position and incidentally also acts to hold the container firmly in position. This holding means is preferably made active shortly after the initial engagement of label and container is had—at a point where the container and label approximate the condition shown in Fig. 37—this clamping action being preserved throughout substantially the remainder of the upward flight of the container.

Various ways of providing such holding means may be employed, a preferred structure being by the use of an endless chain structure in which the link connections carry suitable members 127, which may be in the form of rollers having concave faces which contact with the upper face of the label, as shown more particularly in Fig. 31, these rolls being positioned in the chain structure 126, so as to position a roll directly over each container and its label as the latter

reaches this point. To produce this result I preferably form the chain structure as endless and mounted on supporting rolls 128 and 129 preferably so arranged as to provide a 5 positive drive to the chain structure, this drive being provided from shaft 124 through gear connections on to roll 129, thus bringing this chain structure into the positive drive connections heretofore referred to.

10 As each member 127 passes into engagement practically at the lower portion of roll 128, it will be readily understood that the contract is made in a manner which will not shift the position of the label as the roll 15 passes into clamping position, and since the roll then advances in synchronism with the container, no label shifting action will take place after such engagement is had. This contact of member and label is had during 20 the earlier portion of the end-withdrawing action, and as the roller serves as a clamping member, it will be readily understood that withdrawal of the ends of the label will be positive and without liability of label 25 shifting in the direction of its length due to resistance on the ends of the labels afforded by the particular arrangement, these clamping rollers thus coöperating in properly positioning the label and withdrawing it from 30 its support.

Completion of the end-withdrawal action advances the container and label to a point above the label carrier, as in Fig. 38, after which the band carrier is inactive in the further treatment of the label, the container 35 and label being clamped in position by the correlation of the carrier link structures and rollers 127.

Advancing movement of the clamped container 40 brings it into the path of movement of a pair of wiping devices, shown as in the form of a pair of brushes 130 which are located on opposite sides of the travel path of the container and are adapted to be driven 45 in opposite directions through suitable drive connections with one of the positively driven structures—the drawings showing the drive as from the shaft of roll 129. Brushes 130 are more or less coneshaped in contour, the 50 axes of the brushes extending substantially horizontal and parallel with each other. Consequently, these axes are angular relative to the path of travel of the containers. As shown in Fig. 1^a the brush ends of smallest 55 diameter are in the path of the approaching container, thus providing the greatest space between the brushes at such advance end.

While I may use brushes which have their 60 operating faces corresponding substantially to the face of a cone, I prefer to give the brushes a somewhat irregular shape, as indicated more particularly in Figs. 1^a and 39, this being produced by providing cut out 65 portions of the brushes to permit container

movements without tending to cant the label while being applied. I prefer to do this by reason of the fact that the container is in constant motion in a direction leading toward the larger ends of the brushes; hence, 70 if continuous contact of label and brushes was had, there might be a tendency of the label to be shifted. I therefore prefer to produce a more or less zonal effect to the brushes. For instance, opposing portions 75 of the brushes may be cut away adjacent the entrance, as at 130^a, so that the label of the entering container does not contact with the brush until the container has reached a predetermined part of the brush, at which time 80 a sector of the brush indicated at 130^b, passes into contact with the label and wipes additional portions of the label on to the container body, as indicated, for instance, in Fig. 39. These sector shaped portions 85 become active once during each revolution of the brush, and it will be understood that the container may travel without material brush contact during the remaining portion of the sector travel. Advancing movement of the 90 container brings it to another cut away portion 130^c and into the path of the rear zone 130^d of the brushes, this zone increasing the length of wiping action owing to the fact that the travel of the container has now carried 95 it above the plane of the axes of the brushes so that a condition somewhat like that shown in Fig. 40 takes place, the container passing from the wiping mechanism with the label approximately in the position 100 shown in Fig. 41.

The brush formation is preferably arranged more particularly with respect to the speed of the brushes. In practice I have rotated the brushes at a speed corresponding 105 to the number of containers being labeled per unit of time; for instance, where 300 containers are being labeled, I have rotated the brushes at a speed of 300 revolutions per minute. And in such structure the brushes 110 have been of a length to practically receive three traveling containers at the same time; for instance, one will be located in zone 130^a, another just pass the first sector, and a third approaching its discharge position from the 115 brush. The advantage of this general arrangement is that the wiping action is mainly in a downward direction and so arranged that the advancing movement of the container is substantially ineffective on 120 the wiping action.

The containers, after passing the wiping mechanism just described continue the onward travel, thus reaching the top of wheel 123, where the link structures open, thus releasing the containers from the link-clamping action, the roll clamping action being released after the container has passed through the wiping mechanism, the drawings showing this release as being prior to 130

the time when the link structures begin to open. To prevent the containers from passing out of the conveyer until a desired delivery point is reached, I preferably employ 5 a pair of guide members 131 which act to prevent the containers from rolling sidewise from the conveyer, as indicated in Fig. 4.

As will be readily understood, travel of the open link structures around the periphery of wheel 123 places the containers in a 10 position where they will fall forwardly onto the rear of the preceding link support (Fig. 4), and as this support approaches a horizontal plane intersecting the axis of shaft 124, the container will tend to slide outwardly toward the outer end of the support and if unrestrained would pass out of the conveyer. This latter action is prevented by restraining member 132 against which 15 the portion of the container which was uppermost during the applying mechanism passes into contact, the result being that as the link support continues its movement, this portion of the container will travel in 20 contact with member 132 until a portion of the latter is reached which permits the container to escape, the release portion of member 132 being indicated at 133 in which an 25 opening of sufficient width is provided above a plate 134 which practically forms the bottom of a guide for directing the containers on to a pair of guide supports 135, the movement of the containers being by 30 gravity.

35 As shown in Fig. 32, guide supports 135, are spaced apart a distance to provide sufficient support for the containers, these guide supports being stationary and, if desired, having their advance ends curved. Mounted 40 on shaft 136 below the guide supports, is a wheel 137 which operates between guide supports 135 and which is provided with pockets 137^a, the wheel being positioned so that the pocket walls extend above the top 45 plane of the guide supports during a portion of the travel of the wheel. Wheel 137 is preferably also driven in synchronism with the general mechanism and is preferably so arranged that one of the pockets 50 137^a is in or closely approaching a position where the container being discharged from the conveyer will be received within such pocket although the container is supported on guide supports 135. When the container 55 reaches this position, the movement of wheel 137 causes it to be pushed along guide supports 135 until the pushing wall of the pocket passes out of contact with the container, this wall, for more efficient operation, being in the form of a small roller 137^b.

60 By this mechanism, the container is transferred from the moving carrier to the stationary guide supports 135 without material agitation and by gravitation and immediately moved for a distance at least suffi-

cient to permit the succeeding container to enter the succeeding pocket, the movements being practically free from agitation so that liability of the top becoming loose or a tendency of the contents to sift is practically eliminated. 70

Owing to the fact that the containers are deposited on a stationary support, it will be understood that movements of the containers after reaching the support are provided only by wheel 137 which may be considered as a transfer mechanism for the containers. Consequently, the successive delivery of containers from the conveyer and their advancement individually by the 80 transfer wheel 137 collects them in contact succession on the guide supports 135 along which they are moved by the continual addition of the containers at the advance end of the guides. 85

As will be seen, discharge of the container—which has reached the delivery point with the free ends of the label at the inner side of the container,—will pass the unsecured ends of the label in such manner 90 that this portion of the container will be uppermost when the container enters the pocket of wheel 137. Consequently, the containers which are moved on guide supports 135 have these unsecured ends uppermost, the projecting ends of the moving containers being more or less in approximate alignment on the guide supports. This places these ends in condition to be wiped to their final positions on the containers, thus completing the labeling operation. 95

This wiping action is provided by a pair of wiping brushes 138 having their axes extending parallel to the direction of movement of the containers, the brush faces being of comparatively narrow width but elongated in the direction of their axes. These brushes are connected to operate in unison but in opposite directions and are 105 positioned to follow each other in their wiping activity, as will be seen more particularly in Figs. 32, 43 and 44, this arrangement being preferred in order that the length of the bristles of which each brush 110 is composed may provide for efficient wiping action without, however, bringing the bristles of the opposing brushes into material contact upon completion of the particular wiping cycle, the timing causing one 115 brush to practically follow the other in passing a plane intersecting the axes of the two brushes. The width of the brushes is sufficient to insure proper wiping action, without material liability of being affected 120 by the movements of the containers, and at the same time the length of the brushes is sufficient to insure that all of the passing containers will be wiped in this manner, the inactive portion of the rotative travel of the 125 130

brushes permitting at least the greater portion of the wiped containers to be moved out of the wiping zone and a new supply positioned therein, it being readily understood 5 that a second wiping action on any container may take place without affecting the wiped condition.

This completes the labeling operation, and the containers pass along the guide supports 10 to any desired point, either for packaging or for further manipulation as by the addition of stamps, etc., where such are required.

As will be seen both label and container are in continuous movement from the time 15 of label segregating and container delivery to the container feeding mechanism until the container is deposited upon the guide supports 135, all movements being in timed relationship and in synchronism, so as to automatically 20 present a container and label at the point of initial contact with the elements properly positioned relative to each other to insure the proper positioning of the label on the container. The dwell which is provided 25 in the container travel by the spacing of the pockets of wheel 137 is so slight in point of time as to not materially change the continuity of this movement. This will be readily understood from the fact that with a capacity 30 of three hundred containers per minute, five containers will be delivered each second. Hence, it will be understood that the entire labeling operation is practically with continuously 35 moving elements and the mechanism is made operative thereon in such manner as to not only to properly position the label on the container but also apply it without materially disturbing such position, while the elements are traveling, the entire 40 operation being provided in such manner as to produce a high capacity for the mechanism.

Obviously, the principles of the invention may be obtained by instrumentalities other 45 than those specifically illustrated, or one or more of the mechanisms may be omitted, to meet individual conditions of installation and service. Similarly other forms of such instrumentalities may be substituted, or 50 other changes may be made to meet the problems arising from individual installations. For instance, a low capacity machine may not require the particular type of label or container feed, and it is to be understood 55 that such changes are contemplated within the scope of the present invention. Similarly the required changes or modifications designed to meet particular uses when involving the general principles, are also considered 60 as falling within such scope, it being my desire to reserve the right to make any and all such changes and modifications in the apparatus to meet operating conditions in so far as they may fall within the spirit 65 and wide scope of the invention intended

and as expressed more particularly in the appended claims.

Having thus described my invention, what I claim as new, is:

1. In labeling apparatus for applying labels to containers, instrumentalities for delivering a succession of adhesively-coated labels and a succession of containers into registration contact and to position and partially apply a label to its container while maintaining label ends supported independently of the container, and instrumentalities in the path of travel of the container and its positioned label for completing the label application, said instrumentalities being operatively connected to move in synchronism to maintain a substantially continuous travel of the containers and labels through the apparatus.

2. In labeling apparatus for applying labels to containers, instrumentalities for delivering a succession of adhesively-coated labels and a succession of containers into registration contact and to position and partially apply a label to its container while maintaining label ends supported independently of the container, an instrumentality in the path of travel of the container and its positioned label for increasing the length of label contact, said instrumentalities being operatively connected to move continuously and in synchronism to provide a continuous travel of the containers and labels through said instrumentalities, and an auxiliary instrumentality for completing the label application.

3. In labeling apparatus for applying labels to containers, instrumentalities for delivering a succession of adhesively-coated labels and a succession of containers into registration contact and to position and partially apply a label to its container, and instrumentality in the path of travel of the container and its positioned label for increasing the length of label contact, said instrumentalities being operatively connected to move continuously and in synchronism to provide a continuous travel of the containers and labels through said instrumentalities, successive containers being in spaced relation 115 throughout such continuous travel, means operative in the container travel path for bringing successive containers into contact and advancing them while in contact, and an auxiliary instrumentality operative in the 120 path of the advancing contacting containers for completing the application of the labels.

4. In labeling apparatus for applying labels to containers, instrumentalities for delivering a succession of adhesively-coated labels and a succession of containers into registration contact and to position and partially apply a label to its container while maintaining label ends supported independently of the container, a wiping instrumen- 125

tality in the path of travel of the container and its positioned label for increasing the length of label contact, said instrumentalities being operatively connected to move continuously and in synchronism to provide a continuous travel of the containers and labels through said instrumentalities, and an auxiliary instrumentality for completing the label application.

- 10 5. In labeling apparatus for applying labels to containers, instrumentalities for delivering a succession of adhesively-coated labels and a succession of containers into registration contact and to position and 75
 15 partially apply a label to its container, a wiping instrumentality in the path of travel of the container and its positioned label for increasing the length of label contact, said instrumentalities being operatively connected to move continuously and in synchronism to provide a continuous travel of the containers and labels through said instrumentalities, successive containers being in spaced relation throughout such continuous travel, 80
 20 means operative in the container travel path for bringing successive containers into contact and advancing them while in contact, and an auxiliary wiping instrumentality operative in the path of the advancing contact- 85
 25 30 ing containers for completing the application of the labels.

6. In labeling apparatus for applying labels to containers, a label carrier for supporting a succession of labels and a container carrier for supporting a succession of containers, said carriers being operatively connected for continuous and synchronous movement and having respective travel paths adapted to deliver labels and containers 95
 35 into registration contact and to position and partially apply a label to its container while maintaining label ends supported independently of the container, a wiping instrumentality in the path of travel of the 100
 40 container and its positioned label for increasing the length of label contact, said instrumentalities moving in synchronism with the carriers, and an auxiliary instrumentality for completing the label application.

- 45 50 7. In labeling apparatus for applying labels to containers, a label carrier for supporting a succession of labels and a container carrier for supporting a succession of containers, said carriers being operatively connected for continuous and synchronous movement and having respective travel paths adapted to deliver labels and containers into registration contact and to position and partially apply a label to its container, 105
 55 a wiping instrumentality moving in synchronism with said carriers and located in the path of travel of the container and its positioned label for increasing the length of label contact, said container-carrier main- 110
 60 65 taining successive containers in spaced re-

lation, means for discharging containers from the container-carrier and for advancing the discharged containers with successive containers in contact relation, and an auxiliary wiping instrumentality operative 70 in the path of the advancing contacting containers for completing the application of the label.

8. In labeling apparatus for applying labels to containers, a label carrier for supporting a succession of labels, a container-carrier for supporting a succession of containers in spaced relation, said carriers being operatively connected for continuous and synchronous movement and having travel paths relatively positioned to deliver a label and container into registration contact and to position and partially apply a label to its container while maintaining label ends supported independently of the container, instrumentalities for delivering labels and containers to their respective carriers and for positioning them on such carriers, and instrumentalities in the path of a container and its positioned label for completing the label application.

9. In labeling apparatus for applying labels to containers, a label carrier for supporting a succession of labels, a container carrier for supporting a succession of containers in spaced relation, said carriers being operatively connected for continuous and synchronous movement and having travel paths relatively positioned to deliver a label and container into registration contact and to position and partially apply a label to its container while maintaining label ends supported independently of the container, an instrumentality for feeding a succession of labels to the label carrier, said carrier having means for applying adhesive to the label while traveling to the label-applying position, an instrumentality for delivering containers to the container carrier, and instrumentalities in the path of the advancing container and its positioned label for completing the label application.

10. In labeling apparatus for applying labels to containers, a label carrier for supporting a plurality of labels, said carrier 115 label-supporting face being adapted to adhesively condition the label for label application, an instrumentality for delivering labels to and positioning them on said carrier in spaced succession, a container carrier 120 adapted to support a plurality of containers in spaced relation, with the spacing supplemental to the label spacing, means for operatively connecting said carriers to travel in synchronism to cause registration contact 125 of a label and its container during the carrier movements, and instrumentalities in the path of an advancing container and its positioned label for completing the label application.

11. In labeling apparatus for applying labels to containers, a label carrier for supporting a plurality of labels, an instrumentality for delivering labels to and positioning them on said carrier in spaced succession, a container carrier adapted to support a plurality of containers in spaced relation, with the spacing complementary to the label spacing, an instrumentality for delivering containers to the container carrier successively, means for operatively connecting said carriers to travel in synchronism to cause registration contact of the label and its container during carrier movements while maintaining label ends supported independently of the container, and instrumentalities in the path of an advancing container and its positioned label for completing the label application.
12. In labeling apparatus for applying labels to containers, a label carrier for supporting a plurality of labels, an instrumentality for delivering labels to and positioning them on said carrier in spaced succession, a container carrier adapted to support a plurality of containers in spaced relation, with the spacing complementary to the label spacing, mechanism for delivering containers to the container-carrier successively, said mechanism being adapted to deliver containers laterally and alternately from opposite sides of the path of travel of the container carrier, means for operatively connecting the carriers and said mechanism to move in synchronism, said carriers having relative paths of movement to cause registration contact between a label and its container during carrier movements, and instrumentalities in the path of travel of an advancing container and its positioned label for completing the label application.
13. In labeling apparatus for applying labels to containers, a label carrier for supporting a plurality of labels, a container carrier for supporting a succession of containers, said carriers being operatively connected for continuous and synchronous movements and having travel paths relatively positioned to deliver a label and container into registration contact and to position and partially apply a label to its container during carrier movements, an instrumentality in the travel path of the container carrier and operative on the container and its positioned label during movements of the carrier for increasing the length of label contact, and an instrumentality in the path of an advancing container for completing the label application.
14. In labeling apparatus for applying labels to containers, a label carrier for supporting a plurality of labels, a container carrier for supporting a succession of containers, said carriers being operatively connected for continuous and synchronous movements and having travel paths relatively positioned to deliver a label and container into registration contact and to position and partially apply a label to its container during carrier movements, an instrumentality in the path of the container carrier and operative on the container and its positioned label during movements of the carrier for increasing the length of label contact, and an instrumentality in the path of an advancing container for completing the label application.
15. In labeling apparatus for applying labels to containers, a traveling container carrier for supporting a plurality of containers, a traveling label carrier having a path of movement intersecting the travel path of the container carrier and adapted to deliver the labels into registration contact with containers with the ends of the labels supported by the carrier at the time of contact, said contacting labels and containers having movements in directions to withdraw the labels from the carrier and concurrently position and partially apply the labels to the containers, and mechanism operative on the containers and their positioned labels for completing the label application.
16. In labeling apparatus for applying labels to containers, a traveling label carrier for supporting a plurality of labels and for delivering the labels into registration contact with containers, means for applying adhesive material to predetermined portions of the carrier to cause a face of each label to receive adhesive material during travel of the labels, and means for cleaning the carrier from residue adhesive after removal of the labels from the carrier and prior to adhesive application.
17. In labeling apparatus for applying labels to containers, a traveling label carrier for supporting a plurality of labels and delivering the labels into registration contact with containers, an instrumentality for delivering and positioning the labels on the carrier, said carrier normally having a path of movement in juxtaposition to said instrumentality, means for applying adhesive material to carrier portions in advance of label receipt to provide adhesive application to the label during its travel to applying position, and means controlled by instrumentality operation for automatically shifting the carrier travel path away from such instrumentality under abnormal conditions.
18. In labeling apparatus for applying labels to containers, a traveling container carrier adapted to support a plurality of containers in spaced succession, container supply mechanism including means for placing containers in contact relation, means for transferring containers from the supply to

the container-carrier successively, means for positioning labels on the containers while in spaced relation, means for discharging containers from the carrier and for collecting 5 discharged containers in contact relation, and means for completing the label application while in such contacting relation.

19. In labeling apparatus for applying labels to containers having a circular label-receiving contour, a traveling label carrier for supporting a plurality of labels, said carrier being adapted to deliver the labels to applying position with an intermediate portion unsupported, a container carrier adapted to 15 support a plurality of containers in spaced relation with the label-receiving face extending in directions transverse to the direction of travel of the containers, means whereby containers and unsupported portions of labels will be brought into registration contact, travel of containers on completion of 20 registration contact removing the labels from the carrier and positioning and partially applying the labels to their respective 25 containers, and instrumentalities in the path of an advancing container and its positioned label for completing the label application.

20. In labeling apparatus, a label carrier, a container carrier adapted to support a 30 container with a label-receiving face in parallelism with the path of travel of the label in advancing to the point of label application, and means for moving said carriers in intersecting planes and in synchronization 35 to cause contact of positioned labels and containers at the point of intersection and during travel of the carriers.

21. In labeling apparatus, a label carrier, a container carrier adapted to support a 40 container with a label-receiving face in parallelism with the path of travel of the label in advancing to the point of label application, and means for moving said carriers in intersecting planes and in synchronization 45 to cause registration contact of positioned labels and containers at the point of intersection and during travel of the carriers.

22. In labeling apparatus, a traveling label support, means for positioning a succession 50 of labels at spaced-apart points thereon, a traveling container support movable in a plane intersecting the path of travel of the labels, said container support being adapted to support containers with a label-receiving 55 face in substantial parallelism with the label travel path, means for delivering a succession of containers to the container support, and means for synchronizing the movements of said supports to cause registration contact of positioned labels and such container faces at the point of intersection and during 60 travel of the supports.

23. In labeling machines, a traveling carrier for a succession of labels, a traveling 65 carrier for a succession of containers and

movable in a plane intersecting the travel path of the label carrier, and means for synchronizing the movements of said carriers to provide label contact with and prevent relative slippage movement between the label and container at the point of intersection of the travel paths of a label and a label-receiving face of the container during movements of the carriers. 70

24. In labeling machines, a traveling carrier 75 for a succession of labels with the label movable in a substantially horizontal plane, a traveling carrier for a succession of containers with the containers movable in a direction inclined to and intersecting the plane 80 of label movement, and means whereby a label will be brought into registration contact with a container substantially at the point of intersection of the travel paths of a label and container and during movements 85 of the carriers.

25. In labeling machines, a traveling carrier 90 for a succession of labels with the label movable in a substantially horizontal plane, a traveling carrier for a succession of containers with the containers movable in an upward direction inclined to and intersecting the plane of label movement, and means whereby a label will be brought into registration contact with a container substantially 95 at the point of intersection of the travel paths of a label and container during movements of the carriers.

26. In labeling machines, a traveling carrier 100 for labels movable in a direction transverse to the direction of length of the labels, a traveling carrier for containers movable in a direction intersecting the path of travel of the label and adapted to carry the containers with a label-receiving face extending 105 transverse to the direction of container travel, and means for synchronizing the movements of the carriers to cause registration contact of and prevent relative slippage movement between a label and container at 110 the point of intersection of the travel paths of the label and such container face during movements of the carriers.

27. In labeling machines, a traveling label support, means for positioning a succession 115 of labels thereon with their directions of length transverse to the direction of label movement, a traveling container support, and means for positioning a succession of containers thereon with the label-receiving 120 faces extending transverse to the direction of container travel, said supports having movements in intersecting planes with the movements timed to provide registration contact of and prevent relative slippage 125 movement between successive labels and containers at the point of intersection of the travel paths of a label and container face and during movement of the supports.

28. In labeling apparatus, mechanism for 130

moving a label through a predetermined travel path, mechanism for moving a container through a predetermined travel path intersecting the label travel path, and means 5 for synchronizing the movements of said mechanisms to cause the container to present a label-receiving face to and in registration contact with the traveling label, continued travel of the label-moving means and the 10 continued movement of the container withdrawing the label from its moving means with the registration contact maintained.

29. In labeling apparatus, mechanism for moving an adhesively-coated label through a 15 predetermined travel path, mechanism for moving a container label-receiving face in an inclined path intersecting the label travel path, a portion of the adhesively-coated face of the label being exposed at the point of intersection, and means for synchronizing the 20 movements of said mechanisms to cause registration contact of such traveling exposed label face and the moving container face at such point of intersection and withdraw the 25 label from its moving mechanism with the registration contact maintained during the continued travel of both mechanisms.

30. In labeling apparatus, mechanism for moving an adhesively-coated label through a 30 predetermined travel path, mechanism for moving a container label-receiving face upwardly in an inclined path intersecting the label travel path, a portion of the adhesively-coated face of the label being exposed at 35 the point of intersection, and means for synchronizing the movements of said mechanisms to cause registration contact of such traveling exposed label face and the moving container face at such point of intersection 40 and withdraw the label from its moving mechanism with the registration contact maintained during the continued travel of both mechanisms.

31. In labeling machines, a label carrier 45 adapted to support a label in position normally free to be withdrawn in advance of and during label application, a container carrier adapted to hold a positioned container against movement on an axis, and 50 means for moving said carriers relatively to each other in a manner to successively bring a label and container into registration contact assembly free from relative slippage and withdraw the label from its carrier during 55 continuous movement of the carriers, the label withdrawal being by movements of the assembly.

32. In labeling machines, a label carrier, a container carrier, and means for moving 60 said carriers relatively to each other in a manner to successively bring a label and container into registration contact and withdraw the label from its carrier during continuous movement of the carriers, said label

carrier including a band-formed structure 65 within which the label is positioned.

33. In labeling machines, a label carrier, a container carrier, and means for moving said carriers relatively to each other in a manner to successively bring a label and 70 container into registration contact and withdraw the label from its carrier during continuous movement of the carriers, said label carrier including a plurality of endless bands adapted to receive and support the 75 label ends during such contacting and withdrawal operations.

34. In labeling machines, a label carrier, a container carrier, and means for moving said carriers relatively to each other in a 80 manner to successively bring a label and container into registration contact and withdraw the label from its carrier during continuous movement of the carriers, said label carrier including a pair of spaced-apart endless bands for supporting the ends of the 85 labels, and a pair of endless bands overlying the label ends in opposition to the first mentioned pair.

35. In labeling machines, a label carrier, 90 a container carrier, and means for moving said carriers relatively to each other in a manner to successively bring a label and container into registration contact and withdraw the label from its carrier during 95 continuous movement of the carriers, said label carrier including a pair of spaced-apart bands for receiving the labels and supporting the ends thereof, and a second pair of bands rendered active after the labels have 100 been positioned and adapted to overlie the positioned labels in opposition to the first mentioned pair of bands.

36. In labeling machines, a label carrier, a container carrier, and means for moving 105 said carriers relatively to each other in a manner to successively bring a label and container into registration contact and withdraw the label from its carrier during continuous movement of the carriers, said label 110 carrier including a pair of spaced-apart endless bands for receiving the labels and supporting the ends thereof, and a second pair of endless bands rendered active after the labels have been positioned and adapted 115 to overlie the positioned labels in opposition to the first mentioned pair of bands.

37. In labeling machines, a label carrier, a container carrier, and means for moving said carriers relatively to each other in a 120 manner to successively bring a label and container into registration contact and withdraw the label from its carrier during continuous movement of the carriers, said label carrier including a pair of spaced-apart endless bands for supporting the ends of the labels, and a pair of endless bands overlying the label ends in opposition to the first

mentioned pair, the bands of the first-named pair being of greater width than those of the other pair.

38. In labeling apparatus adapted to deliver a succession of labels for label application to containers, a traveling label carrier adapted to receive and deliver the labels in succession and during carrier travel, and means for adhesively coating a face of each label during travel of the carrier to the point of application.

39. In labeling apparatus adapted to deliver a succession of labels for label application to containers, a traveling label carrier adapted to receive and deliver the labels in succession and during carrier travel, and means for coating a face of the carrier with adhesive prior to receiving the labels, whereby a face of the labels will receive an adhesive-coating during label travel to the point of application.

40. In labeling apparatus adapted to deliver a succession of labels for label application to containers, a traveling label-carrier movable during label receipt and delivery and adapted to support labels during movement to the point of label application, said carrier including a plurality of bands having faces adapted to receive the labels, and means for adhesively coating such faces of said bands prior to receiving the labels.

41. In labeling apparatus adapted to deliver a succession of labels for label application to containers, a traveling label-carrier adapted to support labels during movement to the point of label application, said carrier including a plurality of bands having faces adapted to receive the labels, and means for adhesively coating such faces of said bands prior to receiving the labels, one of said bands being moved out of contact with the label prior to reaching such point of application, whereby an adhesively-coated face of a portion of the label will be exposed at such point of application.

42. In labeling apparatus adapted to deliver a succession of labels for label application to containers, a traveling label-carrier adapted to support labels during movement to the point of label application, said carrier including a plurality of bands having faces adapted to receive the labels, and means for adhesively coating such faces of said bands prior to receiving the labels, an intermediate band being moved out of contact with the label prior to reaching such point of application, whereby the adhesively-coated face of a portion of the label will be exposed at such point of application.

43. In labeling apparatus adapted to deliver a succession of labels for label application to containers, a traveling label-carrier adapted to support labels during movement to the point of label application, said carrier including a plurality of bands hav-

ing faces adapted to receive the labels, one of said bands being moved out of contact with the label prior to reaching such point of application, and means for adhesively coating the label-receiving face of said band prior to label receipt, whereby the label will be delivered at such point of application with an adhesively-coated face portion exposed.

44. In labeling apparatus adapted to deliver a succession of labels for label application to containers, a traveling label-carrier adapted to support the labels during travel to the point of application, said carrier including opposing sets of bands between which the label is carried, one set being adapted to receive the labels in advance of activity of the other set, and means for adhesively-coating a face of the receiving set of bands prior to label receipt, whereby one face of the labels will receive an adhesive-coating during travel to such point of application.

45. In labeling apparatus adapted to deliver a succession of labels for label application to containers, a traveling label-carrier adapted to support the labels during travel to the point of application, said carrier including opposing sets of bands between which the label is carried, one set being adapted to receive the labels in advance of activity of the other set, an additional band positioned to cooperate in the receiving set during label-receiving and advancing movement and movable out of contact therewith prior to label delivery at the point of label application, and means for adhesively coating a face of the receiving set and said additional band prior to label receipt, whereby one face of the labels will receive an adhesive coating during travel to such point of application and a portion of the adhesively-coated label face will be exposed at such point.

46. In labeling apparatus for applying labels to containers, a traveling label carrier adapted to receive and deliver adhesively-coated labels with a portion of the coated face exposed at the point of label application, a traveling container carrier adapted to deliver individual containers at such point of application in registration with the exposed portion of the label, and means whereby continued travel of the container carrier will expose the remainder of the coated face of the label.

47. In labeling apparatus for applying labels to containers, a traveling carrier having an adhesively-coated face for receiving labels and applying an adhesive coating thereto, said carrier being adapted to deliver the labels at a label-applying position with a portion of the coated face exposed, a container carrier movable to intersect the plane of the travel path of the label and present

- a container face to said exposed label face at such applying position, and means whereby continued travel of the container will move such exposed label portion out of such plane and withdraw the unexposed label portions from the carrier.
48. In labeling apparatus for applying labels to containers, a traveling carrier having an adhesively-coated face for receiving labels and applying an adhesive coating thereto, said carrier being adapted to deliver the labels at a label-applying position with a portion of the coated face exposed, a container carrier movable to intersect the plane of the travel path of the label and present a container face to said exposed label face at such applying position, and means whereby continued travel of the container will move such exposed label portion out of such plane and withdraw the unexposed label portions from the carrier, the direction of container movement during such withdrawal increasing the contact zone of label and container.
49. In labeling apparatus for applying labels to containers, a traveling carrier for delivering labels to a point of label application, said carrier including opposing sets of bands one set having an adhesively-coated face and being adapted to receive the labels, the other set being adapted to overlie the labels and retain them positioned on the receiving set with an adhesively-coated face portion of the label exposed, a traveling carrier for presenting a label-receiving face to the exposed face of the traveling label, said container-carrier being movable to intersect the plane of the label traveling path, and means whereby continued travel of the container will withdraw the label from such carrier in opposition to the restraint offered by the bands, the direction of container movement during label withdrawal increasing the contact zone of label and container.
50. In labeling apparatus adapted to move individual labels and containers into registration contact for label-applying action, a traveling band-formed label carrier adapted to support opposite ends of the label with an intermediate portion of the label adhesively conditioned and exposed, and a container carrier having a travel path extending through and to opposite sides of the label carrier with a path of movement within the unsupported zone of the label, said carriers being movable to provide such registration contact during carrier travel at the point of intersection of the planes of the travel paths of the moving label and label-receiving face of the container.
51. In labeling apparatus adapted to move individual labels and containers into registration contact for label-applying action, a traveling label-carrier including spaced-apart bands for supporting the label, a container-carrier movable through the space between said bands, and means for synchronizing the movements of said carriers to bring a label and container into registration contact and to prevent relative slippage movement therebetween at the point of intersection of the travel paths of the moving label and container label-receiving face.
52. In labeling apparatus adapted to move individual labels and containers into registration contact for label-applying action, a traveling label-carrier including spaced-apart bands for supporting the label, a container-carrier movable through the space between said bands, and in an upward direction inclined to the path of travel of the label carrier, and means for synchronizing the movements of said carriers to bring a label and container into registration contact at the intersection of the travel paths of the moving label and container label-receiving face.
53. In labeling machines, a label carrier, a container carrier, and means for moving said carriers relatively to each other in a manner to successively bring a label and container into registration contact and withdraw the label from its carrier during continuous movement of the carriers, said label carrier including a pair of spaced-apart endless bands for supporting the ends of the labels, and a pair of endless bands overlying the label ends in opposition to the first mentioned pair, said container carrier being movable through the space between said spaced-apart bands.
54. In labeling machines, a label carrier, a container carrier, and means for moving said carriers relatively to each other in a manner to successively bring a label and container into registration contact and withdraw the label from its carrier during continuous movement of the carriers, said label carrier including a pair of spaced-apart endless bands for supporting the ends of the labels, and a pair of endless bands overlying the label ends in opposition to the first mentioned pair, said container carrier being movable in an upward direction inclined to the path of travel of the label and through the space between said spaced-apart bands.
55. In labeling machines, a traveling label carrier, a traveling carrier for containers adapted to move a container label-receiving face across the plane of the path of travel of the label, said container carrier including a link structure having a plurality of individual compartments to receive individual containers, and means for successively opening and closing said compartments during travel of the link structure to permit introduction of the containers, open-

ing and closing of each compartment taking place prior to presenting the container within the label travel path.

56. In labeling machines, a traveling label carrier, a traveling carrier for containers adapted to move a container label-receiving face across the plane of the path of travel of the label in a direction inclined upwardly relative to said path, said container carrier including a link structure having a plurality of individual compartments to receive individual containers, and means for successively opening and closing said compartments during travel of the link structure to permit 10 introduction of the containers, opening and closing of each compartment taking place prior to presenting the container within the label travel path.

57. In labeling machines, a traveling label carrier, a traveling carrier for containers adapted to move a container label-receiving face across the plane of the path of travel of the label, said container carrier including a link structure having a plurality of 20 individual compartments to receive and clamp individual containers therein, and means for successively opening and closing the compartments during travel to permit introduction of the containers to position 25 and clamping of the positioned containers, said means being rendered active on the link structure in advance of container presentation within the label travel path.

58. In labeling machines, a traveling label carrier, a traveling carrier for containers adapted to move a container label-receiving face across the plane of the path of travel of the label, said container carrier including a link structure adapted to form a plurality 35 of container-receiving compartments, each compartment having a seating structure for the container, and means for successively opening and closing the compartments during travel of the link structure to permit 40 the introduction and positioning of a container therein and the clamping of the positioned container, said means being rendered active on the link structure in advance 45 of container presentation within the label travel path.

59. In labeling machines, a traveling label carrier, a traveling carrier for containers adapted to move a container label-receiving face across the plane of the path of travel 55 of the label, said container carrier including an endless link-formed structure having spaced outwardly projecting arms to form individual container-receiving compartments, container seating and positioning elements carried by said arms and extending 60 into the several compartments, and means for moving said link structure through a travel path intersecting the label travel path and with a portion of its path in advance of 65 such point of intersection curved to auto-

matically and successively open and close said compartments to permit introduction of an individual container into and its positioning within a compartment and clamping of the container therein.

60. In labeling machines, a traveling label carrier, a traveling carrier for containers adapted to move a container label-receiving face across the plane of the path of travel of the label, said container carrier including 70 an endless link-formed structure having spaced outwardly projecting arms to form individual container-receiving compartments, container seating and positioning elements carried by said arms and extending 75 into the several compartments, and means for moving said link structure through a travel path intersecting the label travel path and with a portion of its path in advance 80 of such point of intersection curved to automatically and successively open and close said compartments to permit introduction of an individual container into and its positioning within a compartment and clamping 85 of the container therein, said link-formed structure having a configuration whereby the arms and positioning element will move the container to the point of label application with a container label-receiving 90 face extending in parallelism with the label 95 travel path.

61. In labeling machines, label-presenting mechanism, a traveling carrier for individual containers adapted to move the containers into label-receiving position, said 100 carrier including an endless link-formed structure adapted to form a plurality of container-receiving compartments, each compartment having a rigid seating and positioning structure for the container, and 105 means for moving said link structure through a path of travel adapted to successively open and close the compartments to permit introduction and positioning of a 110 container therein during travel to such label-receiving position.

62. In labeling machines, label-presenting mechanism, a traveling carrier for individual containers adapted to move the containers into label-receiving position, said carrier including an endless link-formed structure adapted to form a plurality of container-receiving compartments, each compartment having opposing rigid walls normally positioned to clamp a container and 115 also having a seating and positioning structure for the container, and means for moving said link structure through a path of travel adapted to successively shift said compartment walls to open and close the compartment during travel of the container to its label-receiving position, whereby the container may be introduced and automatically 120 positioned and clamped in such position during such travel.

63. In labeling machines, label-presenting mechanism, a traveling carrier for individual containers adapted to move a succession of containers into label-receiving position, said carrier including a link-formed structure adapted to form a plurality of container-receiving compartments, container feeding mechanism operative to deliver individual containers in the path of travel of the carrier, and means for opening each compartment as it approaches the delivery point of said mechanism and for closing the compartment after the container has been received and prior to reaching the label-receiving position.

64. In labeling machines, label-presenting mechanism, a traveling carrier for individual containers adapted to move a succession of containers into label-receiving position, said carrier including a link-formed structure adapted to form a plurality of container-receiving compartments, container feeding mechanism operative to deliver individual containers laterally in the path of travel of the carriers, and means for opening each compartment as it approaches the delivery point of said mechanism and for closing the compartment after the container has been received and prior to reaching the label-receiving position.

65. In labeling machines, label-presenting mechanism, a traveling carrier for individual containers adapted to move a succession of containers into label-receiving position, said carrier including a link-formed structure adapted to form a plurality of container-receiving compartments, rotatable container feeding mechanism adapted to deliver individual containers laterally into the path of travel of the carrier, and an element rotatable with said mechanism and co-operative with said carrier during carrier movements, said element being operative to produce compartment-opening as a compartment approaches the delivery point of said mechanism and compartment-closing after the compartment has been positioned and prior to its reaching the label-receiving position.

66. In labeling machines, label-presenting mechanism, a traveling carrier for individual containers adapted to move a succession of containers into label-receiving position, said carrier including a link-formed structure adapted to form a plurality of container-receiving compartments, container feeding mechanism operative to deliver individual containers into the path of travel of the carrier, said feeding mechanism including feeding devices positioned on opposite sides of the carrier travel path and operative to deliver the containers laterally into such travel path.

67. In labeling machines, label-presenting mechanism, a traveling carrier for indi-

vidual containers adapted to move a succession of containers into label-receiving position, said carrier including a link-formed structure adapted to form a plurality of container-receiving compartments, container feeding mechanism operative to deliver individual containers into the path of travel of the carrier, said feeding mechanism including feeding devices positioned on opposite sides of the carrier travel path and operative to deliver the containers laterally into such travel path with the containers fed alternately from the devices.

68. In labeling machines, label-presenting mechanism, a traveling carrier for individual containers adapted to move a succession of containers into label-receiving position, said carrier including a link-formed structure adapted to form a plurality of container-receiving compartments, container feeding mechanism operative to deliver individual containers into the path of travel of the carrier, said feeding mechanism including feeding devices positioned on opposite sides of the carrier travel path and operative to deliver the containers laterally into such travel path with alternate containers fed from the same device.

69. In labeling machines, label-presenting mechanism, a traveling carrier for individual containers adapted to move a succession of containers into label-receiving position, said carrier including a link-formed structure adapted to form a plurality of container-receiving compartments, rotatable container feeding mechanism adapted to deliver individual containers laterally into the path of travel of the carrier, said mechanism including container-feeding devices positioned on opposite sides of the carrier travel path and operative alternately in delivering the succession of containers, and means for successively opening each compartment as it approaches such delivery position to receive the delivered container and for closing the compartments after the container has been positioned.

70. In labeling machines, a label carrier, adapted to move a label in the plane of its face, a container carrier, means for moving said carriers to produce registration contact between a label and a container-receiving face during label carrier movements, mechanism for increasing the area of contact of label and container, and means for clamping the label in position in advance of mechanism activity.

71. In labeling machines, a label carrier, adapted to move a label in the plane of its face, a container carrier, means for moving said carriers to produce registration contact between a label and a container-receiving face during label carrier movements, mechanism for increasing the area of contact of label and container, said mechanism

being positioned in the travel path of the container and operative on positioned labels, and means for clamping the positioned label in advance of mechanism activity.

- 5 72. In labeling machines, a traveling container carrier adapted to present a container-receiving face to a label during such travel, an element independent of and movable in synchronism with the carrier for clamping 70 the positioned label to such face during predetermined portions of the carrier travel, and means independent of the container for moving said element.

15 73. In labeling machines, a traveling container carrier adapted to present a container-carrier face to a label during such travel, said carrier including a link-formed structure adapted to form compartments to receive a succession of containers, and an end-20 less element movable in synchronism with the carrier and having members positioned to engage the positioned labels during predetermined portions of carrier travel.

25 74. In labeling machines, a traveling container carrier adapted to support a succession of containers with positioned labels, and rotatable label wiping means in the path of travel of the carrier, said carrier having a path of travel including a flight angular to 90 the direction of axial length of the wiping means.

30 75. In labeling machines, a traveling container carrier adapted to support a succession of containers with positioned labels, and rotatable label wiping means in the path of travel of the carrier, said carrier having a path of travel including an upwardly moving flight inclined to the direction of axial length of the wiping means.

40 76. In labeling machines, a traveling container carrier adapted to support a succession of containers with positioned labels, and rotatable label wiping means in the path of travel of the carrier, said means including 95 a pair of brushes on opposite sides of the carrier travel path, said carrier having a path of travel including an upwardly moving flight inclined to the axes of said brushes.

45 77. In labeling machines, a traveling container carrier adapted to support a succession of containers with positioned labels, and rotatable label wiping means in the path of travel of the carrier, said means including 100 a pair of brushes on opposite sides of the carrier travel path, said carrier having a path of travel including an upwardly moving flight inclined to the axes of said brushes, said brushes having parallel axes,

50 55 60 each brush having its advance end of less diameter than its rear end.

78. In labeling machines, a traveling container carrier adapted to support a succession of containers with positioned labels, and 65 rotatable label wiping means in the path of

travel of the carrier, said means including a pair of brushes on opposite sides of the carrier travel path, said carrier having a path of travel including an upwardly moving flight inclined to the axes of said brushes, said 70 brushes having parallel axes and each having a longitudinal facial contour of unsymmetrical cone shape.

79. In labeling machines, a traveling container carrier adapted to support a succession of containers with positioned labels, and rotatable label wiping means in the path of travel of the carrier, said means including a pair of brushes on opposite sides of the carrier travel path, said carrier having a path of travel including an upwardly moving flight inclined to the axes of said brushes, said brushes having parallel axes and each having a longitudinal facial contour of unsymmetrical cone shape, with the 85 advance end of smaller diameter.

80. In labeling machines, a traveling container carrier adapted to support a succession of containers with positioned labels, and rotatable label wiping means in the path 90 of travel of the carrier, said means including a pair of brushes on opposite sides of the carrier travel path, said carrier having a path of travel including an upwardly moving flight inclined to the axes of said 95 brushes, said brushes having parallel axes and each having a facial contour generally increasing in diameter from its advance end, a longitudinal face of the brush being varied to provide active and inactive zones of brush 100 wiping action.

81. In labeling machines, a traveling container carrier adapted to support a succession of containers, with positioned labels, and rotatable label wiping means in the 105 path of travel of the carrier, said means including a pair of brushes on opposite sides of the carrier travel path, said carrier having a path of travel including an upwardly moving flight inclined to the axes of said 110 brushes, said brushes having parallel axes and each having its facial contour varied from a circular form on a cross-section of the brush.

82. In labeling machines, a traveling container carrier adapted to support a succession of containers with positioned labels, and rotatable label wiping means in the path of travel of the carrier, said means including a pair of brushes on opposite sides of the 120 carrier travel path, said carrier having a path of travel including an upwardly moving flight inclined to the axes of said brushes, said brushes having parallel axes and each having its facial contour varied 125 from a circular form on predetermined cross-sections of the brush.

83. In labeling machines, a container carrier adapted to support a container with positioned label, and rotatable wiping means 130

in the path of travel of the carrier, means for moving the container through the sphere of activity of the wiping means and with a continuous motion, said wiping means having its wiping face configuration adapted to provide intermittent wiping action of short duration on the label, whereby container travel will be ineffective to provide material label shifting during the wiping operation.

84. In labeling machines, a container carrier adapted to support a succession of containers with positioned labels, rotatable label wiping means in the path of travel of the carrier, said means having a length to accommodate for concurrent activity on a plurality of containers, and means for moving the containers through the sphere of activity of the wiping means with a continuous motion, said wiping means having its wiping face configuration adapted to provide intermittent wiping action of short duration on the labels, whereby container travel will be ineffective to provide material label shifting during the wiping operation.

85. In labeling machines, a container carrier adapted to support a container with positioned label, wiping brushes positioned on opposite sides of the path of travel of the carrier, and means for moving the containers through the sphere of activity of the brushes with a continuous motion, each of said brushes having its wiping face configuration adapted to provide intermittent wiping action of short duration on the label with successive wipings active on different portions of the label, whereby the positions of the brushes relative to the container travel path in coöperation with the brush configuration will render the wiping operation ineffective to materially shift the label.

86. In labeling machines, a container carrier adapted to support a succession of containers with positioned labels, rotatable label wiping brushes positioned on opposite sides of the path of travel of the carrier with the direction of brush axes angular to the direction of container travel, said brushes each having a length sufficient to accommodate for a plurality of containers, and means for moving the containers through the sphere of activity of the brushes with a continuous motion, the direction of container travel through such sphere and the wiping face configuration of the brushes co-operating to provide intermittent wiping action of short duration on each label with successive wipings effective on different portions of the label.

87. In labeling machines, a container carrier adapted to support a container with positioned label, rotatable label wiping means in the path of travel of the carrier

and adapted to increase the area of label contact with the container, wiping mechanism for completing the label wiping action, and means for delivering the container to said mechanism with its unwiped portion positioned within the operating sphere of the mechanism.

88. In labeling machines, a container carrier adapted to support a succession of containers with positioned labels, rotatable label wiping means in the path of travel of the carrier, and adapted to increase the area of label contact with its container, a container runway for receiving the containers from said carrier, wiping mechanism operative on the containers positioned on the runway for completing the label wiping action, and means for delivering the containers from the carrier to said runway in a manner to present unwiped portions of the labels within the wiping sphere of said mechanism during container travel on the runway.

89. In labeling machines, a label-positioning instrumentality, a rotatable wiping instrumentality, a container carrier having a travel path through which the carrier is adapted to move a succession of containers through said label positioning and wiping instrumentalities to apply a label to each container with the major portion of the label in positioned contact with its container, wiping mechanism for completing the label wiping action and operative after the containers have been delivered from the carrier, and means for transferring the containers from the carrier to said mechanism with the unwiped portions of the label positioned to receive mechanism action.

90. In labeling machines, label-positioning and wiping instrumentalities, a container carrier having a travel path through which the carrier is adapted to move a succession of containers through said label positioning and wiping instrumentalities with a continuous motion to apply a label to each container with the major portion of the label in positioned contact with its container, wiping mechanism for completing the label wiping action and operative after the containers have been delivered from the carrier, and means for transferring the containers from the carrier to said mechanism with the unwiped portions of the label positioned to receive mechanism action.

91. In labeling machines, label-positioning and wiping instrumentalities, a container carrier having a travel path through which the carrier is adapted to move a succession of containers through label positioning and wiping instrumentalities with a continuous motion to apply a label to each container with the major portion of the label in positioned contact with its container, wiping mechanism for completing label wiping

action, and means for moving the containers through the mechanism zone of activity with an intermittent motion.

92. In labeling apparatus, label-positioning and wiping instrumentalities, a container carrier having a travel path through which the carrier is adapted to move a succession of containers in spaced-apart relation and with a continuous container movement through label positioning and wiping instrumentalities to apply a label thereto with the major portion of the label in positioned contact with the container, wiping mechanism for completing label wiping action, and means for moving the containers through the mechanism zone of activity with the containers in contact relation.

93. In labeling machines, label-positioning and wiping instrumentalities, a container carrier having a travel path through which the carrier is adapted to move a succession of containers through label positioning and wiping instrumentalities to apply a label thereto with the major portion of the label in positioned contact with the container, wiping mechanism for completing the label wiping action, a stationary container runway leading to said mechanism and adapted to receive the containers successively from the carrier, and a rotatable transfer device operative to advance the containers on said runway.

94. In labeling machines, label-positioning and wiping instrumentalities, a container carrier having a travel path through which the carrier is adapted to move a succession of containers through label positioning and wiping instrumentalities to apply a label thereto with the major portion of the label in positioned contact with the container, wiping mechanism for completing the label wiping action, a container runway leading to said mechanism and adapted to receive the containers successively from the carrier, and a rotatable transfer device operative to advance the containers on said runway, said device moving in synchronism with the carrier and having pockets into which the containers pass when delivered from the carrier, rotation of the device successively shifting delivered containers out of the path of containers being delivered.

95. In labeling machines, label-positioning and wiping instrumentalities, a container carrier having a travel path through which the carrier is adapted to move a succession of containers with a continuous container movement through label positioning and wiping instrumentalities to apply a label thereto with the major portion of the label in positioned contact with the container, wiping mechanism for completing the wiping action, and means for delivering the containers to said mechanism, said mechanism including wiping brushes positioned

on opposite sides of the container travel path.

96. In labeling machines, label-positioning and wiping instrumentalities, a container carrier having a travel path through which the carrier is adapted to move a succession of containers with a continuous container movement through label positioning and wiping instrumentalities to apply a label thereto with the major portion of the label in positioned contact with the container, wiping mechanism for completing the wiping action, and means for delivering the containers to said mechanism, said mechanism including a pair of brushes each movable in a circular path and adapted to provide intermittent wiping contact with the labels during container movement.

97. In labeling machines, label-positioning and wiping instrumentalities, a container carrier having a travel path through which the carrier is adapted to move a succession of containers through label positioning and wiping instrumentalities to apply a label thereto with the major portion of the label in positioned contact with the container, wiping mechanism for completing the wiping action, and means for delivering the containers to said mechanism, said mechanism including a pair of brushes each movable in a circular path and adapted to provide intermittent wiping contact with the labels during container movement, said brushes being operatively connected to provide non-concurrent wiping activity.

98. In labeling machines, label-positioning and wiping instrumentalities, a container carrier having a travel path through which the carrier is adapted to move a succession of containers through label positioning and wiping instrumentalities to apply a label thereto with the major portion of the label in positioned contact with the container, wiping mechanism for completing the label wiping action, and operative on the unwiped opposite ends of the label, and means for transferring the containers from the carrier into and through said mechanism, said wiping mechanism being operative to wipe the opposite ends of a label in succession.

99. In labeling apparatus, label wiping mechanism adapted to wipe the ends of a label into contact with a container on which the label is positioned, said mechanism including a pair of brushes mounted to travel in a circular path and having a length to operate on a plurality of labels concurrently, a runway for the containers leading to said mechanism and adapted to position the containers in the path of travel of the brushes, and means operative in synchronism with the wiping mechanism for advancing the containers on the runway, the width of the brush faces and the relative

- speeds of brush rotation and container advance permitting positioning and removal of a plurality of containers between successive wiping operations.
- 5 100. In labeling apparatus, label wiping mechanism adapted to wipe the ends of a label into contact with a container on which the label is positioned, said mechanism including a pair of brushes mounted to travel 10 in a circular path and having a length to operate on a plurality of labels concurrently, a runway for the containers leading to said mechanism and adapted to position the containers in the path of travel of the 15 brushes, and means operative in synchronism with the wiping mechanism for advancing the containers on the runway, said brushes being operatively connected to wipe the opposite ends of a label successively.
- 20 101. In labeling machines, label-presenting mechanism, a traveling container carrier for supporting a succession of containers during label positioning, and means for feeding the containers successively to said 25 carrier during carrier travel, said means including a source of container supply, and a rotatable device adapted to receive the containers successively from the supply source and successively transfer them to the carrier while both device and carrier are moving.
- 30 102. In labeling machines, label-presenting mechanism, a traveling container carrier for supporting a succession of containers 35 during label positioning, and means for feeding the containers successively to said carrier during carrier travel, said means including a source of container supply, and a rotatable device movable in synchronism 40 with the carrier and adapted to receive the containers successively from the supply source and successively transfer them to the carrier while both device and carrier are moving.
- 45 103. In labeling machines, label-presenting mechanism, a traveling container carrier for supporting a succession of containers during label positioning, and means for feeding the containers successively to said 50 carrier during carrier travel, said means including a source of container supply, a rotatable device having pockets adapted to receive the containers individually from such source, and a member positioned to 55 control the discharge of containers from said pockets into the path of travel of the carrier.
- 60 104. In labeling machines, label-presenting mechanism, a traveling container carrier for supporting a succession of containers during label positioning, and means for feeding the containers successively to said carrier during carrier travel, said means including a source of container supply, a ro- 65 tatable device having pockets adapted to re-
- ceive the containers individually from such source and a member positioned intermediate the device and the carrier for controlling the discharge of containers from said pockets into the path of travel of the container. 70
105. In labeling machines, label-presenting mechanism, a traveling container carrier for supporting a succession of containers during label positioning, and means for feeding the containers successively to said 75 carrier during carrier travel, said means including a source of container supply, a rotatable device having pockets adapted to receive the containers individually from such source, and a member positioned intermediate 80 the device and the carrier for controlling the discharge of containers from said pockets into the path of travel of the container, said device and carrier being relatively positioned to provide container discharge 85 movements in a direction transverse to the direction of movement of the carrier.
106. In labeling machines, label-presenting mechanism, a traveling container carrier for supporting a succession of containers 90 during label positioning, and means for feeding the containers successively to said carrier during carrier travel, said means including a source of container supply, a rotatable device having pockets adapted to receive the containers individually from such 95 source, and a member positioned intermediate the device and the carrier for controlling the discharge of containers from said pockets into the path of travel of the container, said device and carrier being relatively positioned to provide container discharge 100 movements in a direction transverse to the direction of movement of the carrier, said device having means for transferring 105 the container from receiving to discharging position substantially free from container agitation.
107. In labeling machines, label-presenting mechanism, a traveling container carrier 110 for supporting a succession of containers during label positioning, and means for feeding the containers successively to said carrier during carrier travel, said means including a source of container supply, a rotatable device having a series of pockets to receive the containers individually from such source, each pocket being adapted to receive its container during upward travel of the pocket, and a member positioned to control the discharge of containers from said 115 pockets into the path of travel of the carrier, said member being active to discharge the containers when said pocket is substantially at its lower position, said device having 120 means to transfer the container from receiving to discharging position during device travel carrying the pocket from receiving position to the plane of the container discharging position. 125

108. In labeling machines, label-presenting mechanism, a traveling container carrier for supporting a succession of containers during label positioning, and means for feeding the containers successively to said carrier during carrier travel, said means including a pair of container runways each carrying a succession of containers, means for discharging the containers individually from the runways, and a pair of devices rotatable in the path of discharging containers and adapted to receive individual containers from the runways successively during device rotation, said devices being positioned with respect to the carrier delivery, in a manner to deliver containers thereto successively from different devices.
109. In labeling machines, label-presenting mechanism, a traveling container carrier for supporting a succession of containers during label positioning, and means for feeding the containers successively to said carrier during carrier travel, said means including a pair of container runways each carrying a series of containers, means for controllably discharging containers individually from the runways, and a pair of devices rotatable in the path of discharging containers, each device having pockets adapted to receive the containers individually as discharged, and a member for each device for controlling the discharge of individual containers from its device into the path of travel of the carrier.
110. In labeling machines, label-presenting mechanism, a traveling container carrier for supporting a succession of containers during label positioning, and means for feeding the containers successively to said carrier during carrier travel, said means including a pair of container runways each carrying a series of containers, means for controllably discharging containers individually from the runways, and a pair of devices rotatable in the path of discharging containers, each device having pockets adapted to receive the containers individually as discharged, and a member for each device for controlling the discharge of individual containers from its device into the path of travel of the carrier, said devices being relatively positioned to provide container discharge from the devices into such path of travel alternately.
111. In labeling apparatus, a label carrier adapted to present a label at label-applying position with an intermediate adhesively-coated face exposed, a traveling container carrier movable across the plane of the path of travel of said exposed portion of the label and adapted to present a container to such exposed portion, and means below the plane of the label travel path for feeding a succession of containers to the container carrier, said means being adapted to receive

and discharge the containers in different vertical planes to transfer the container from a plane outside of the label travel path to a plane intersecting such path.

112. In labeling apparatus, a label carrier adapted to present a label at label-applying position with an intermediate adhesively-coated face exposed, a traveling container carrier movable across the plane of the path of travel of said exposed portion of the label and adapted to present a container to such exposed portion, and rotatable means for delivering a succession of containers to said container carrier, said means being adapted to receive and discharge its containers in different vertical planes to permit container discharge beneath the label carrier and container receipt outside of said label carrier, said means having mechanism operative to shift each container from one plane to the other during rotation of said means from receiving to discharge positions.

113. In labeling apparatus, a label carrier adapted to present a label at label-applying position with an intermediate adhesively-coated face exposed, a traveling container carrier movable across the plane of the path of travel of said exposed portion of the label and adapted to present a container to such exposed portion, and rotatable means for delivering a succession of containers to said container carrier, said means being adapted to receive and discharge its containers in different vertical planes to permit container discharge beneath the label carrier and container receipt outside of said label carrier, said means including pocket and guide structures adapted to lead the containers from the receiving to the discharging plane during rotation of the means between container receiving and discharging positions.

114. In labeling apparatus, a movable label carrier for supporting a plurality of labels and adapted to advance the labels to label-applying position, said carrier being adapted to present the labels in such position with a portion of the label unsupported, mechanism for delivering containers into registration-contact with the unsupported portions of labels, and means for delivering a succession of labels to the carrier, said means including a label picker movable in synchronism with the carrier to deliver individual labels to and position them on said carrier.

115. In labeling apparatus, a movable label carrier for supporting a plurality of labels and adapted to advance the labels to label-applying position, said carrier being adapted to present the labels in such position with a portion of the label unsupported, mechanism for delivering containers into registration-contact with the unsupported portions of labels, and means for delivering

- a succession of labels to the carrier, said means including a label picker movable in synchronism with the carrier to deliver individual labels to and position them on said carrier, and means for applying an adhesive coating to the contacting face of each label during its advance to label-applying position.
116. In labeling apparatus, a movable label carrier for supporting a plurality of labels and adapted to advance the labels to label-applying position, mechanism for delivering containers into registration contact with labels at such label-applying position, and means for delivering a succession of labels to the carrier, said means including a label picker movable in synchronism with the carrier to deliver individual labels to and position them on the carrier, said carrier having means for applying adhesive to label faces during travel between label-receiving and label-applying positions.
117. In labeling apparatus, a label carrier for supporting a plurality of individual labels at the label ends and for advancing the labels to label-applying position with intermediate portions of the labels adhesively-conditioned and unsupported in such position, said labels being located in uniformly spaced succession, and means for moving containers into registration contact with unsupported portions of the labels during label travel.
118. In labeling apparatus, a label carrier for supporting a plurality of individual labels at the label ends and for advancing the labels to label-applying position with intermediate portions of the labels adhesively-conditioned and unsupported in such position, said labels being located in uniformly spaced succession, and means for moving containers into registration contact with unsupported portions of the labels, and for removing the labels during label travel from the carrier by container movements.
119. In labeling apparatus, a traveling carrier for presenting labels in the path of moving containers, and means for delivering individual labels to the carrier and positioning them thereon in uniformly spaced succession, said means including a label supply, and a label picker for transferring individual labels from the supply to the carrier, said picker being movable in synchronism with the carrier.
120. In labeling apparatus, a traveling carrier for presenting labels in the path of moving containers, and means for delivering individual labels to the carrier and positioning them thereon in uniformly spaced succession, said means including label supply mechanism, and label picker mechanism, said mechanisms being movable in synchronism with each other and with the carrier.
121. In labeling apparatus, a traveling carrier for presenting labels in the path of moving containers, and means for delivering individual labels to the carrier and positioning them thereon in uniformly spaced succession, said means including a rotatable supply mechanism, and a rotatable label picker mechanism, said mechanisms being operatively connected to travel in synchronism with each other and with the label carrier.
122. In labeling apparatus, a traveling carrier for presenting labels in the path of moving containers, and means for delivering individual labels to the carrier and positioning them thereon in uniformly spaced succession, said means including rotatable label supply and picker mechanisms, said label picker mechanism including a drum having a plurality of label-carrying faces adapted to be successively presented to the label-supply, and means for causing a supply label to adhere to a face during a predetermined length of travel of the drum.
123. In labeling apparatus, a traveling carrier for presenting labels in the path of moving containers, and means for delivering individual labels to the carrier and positioning them thereon in uniformly spaced succession, said means including rotatable label supply and picker mechanisms, said label picker mechanism including a drum having a plurality of label-carrying faces adapted to be successively presented to the label supply, suction mechanism, and means for operatively connecting said suction mechanism to a face during a predetermined length of travel of such face.
124. In labeling apparatus, a traveling carrier for presenting labels in the path of moving containers, and means for delivering individual labels to the carrier and positioning them thereon in uniformly spaced succession, said means including rotatable label supply and picker mechanisms, said label picker mechanism including a drum having a plurality of label-carrying faces adapted to be successively presented to the label supply, a chamber adapted to communicate with a plurality of drum faces concurrently, and suction mechanism in communication with said chamber.
125. In labeling apparatus, a traveling carrier for presenting labels in the path of moving containers, and means for delivering individual labels to the carrier and positioning them thereon in uniformly spaced succession, said means including rotatable label supply and picker mechanisms, said label picker mechanism including a drum having a plurality of label-carrying faces adapted to be successively presented to the label-supply, a chamber adapted to communicate with one or more of the drum faces, suction mechanism in communication with

said chamber, and controllable means for varying the number of faces which may be in communication with the chamber concurrently.

- 5 126. In labeling apparatus, a traveling carrier for presenting labels in the path of moving containers, and means for delivering individual labels to the carrier and positioning them thereon in uniformly spaced 10 succession, said means including rotatable label supply and picker mechanisms, said label picker mechanism including a drum having a plurality of label-carrying faces adapted to be successively presented to the 15 label-supply, a member in operative relation to said drum and having a chamber adapted to communicate with one or more of said drum faces, an element coöperating with the member to form a wall of said 20 chamber, said member being shiftable to control the position of said wall, and suction mechanism in communication with said chamber.

127. In labeling apparatus, a traveling 25 carrier for presenting labels in the path of moving containers, and means for delivering individual labels to the carrier and positioning them thereon in uniformly spaced succession, said means including rotatable 30 label supply and picker mechanisms, said label picker mechanism including a drum having a plurality of label-carrying faces adapted to be successively presented to the label-supply, suction mechanism operative 35 to cause a label to adhere to a drum during a predetermined length of travel of the drum, and means for rendering said suction mechanism inactive on the label to release the label at the end of such label travel.

- 40 128. In labeling apparatus, a traveling carrier for presenting labels in the path of moving containers, and means for delivering individual labels to the carrier and positioning them thereon in uniformly spaced 45 succession, said means including label supply and picker mechanisms operatively connected together to deliver supplied labels to the carrier, said supply mechanism including a rotatable device having a plurality 50 of pockets each adapted to receive a pack of labels, means in the pockets for retaining the outermost label at the outer end of the pocket, rotation of the device causing the outer ends of the pockets to be successively 55 placed in operative relation to a face of the picker mechanism, and means carried by the picker mechanism to withdraw such outer label from the pack when such face is in position.

- 60 129. In labeling apparatus, a traveling label-carrier adapted to support a succession of labels and deliver them into the path of movement of containers, means traveling in synchronism with the carrier for delivering 65 and positioning the labels on the carrier,

and means rendered active in the presence of an imperfect label for shifting the carrier.

130. In labeling apparatus, a traveling label-carrier adapted to support a succession 70 of labels and deliver them into the path of movement of containers, said carrier having a face adapted to apply adhesive to the label during label travel, means traveling in synchronism with the carrier for delivering and 75 positioning the labels on the carrier, and means active in the presence of an imperfect label for shifting the adhesive-applying face away from the path of travel of the label-positioning means. 80

131. In labeling apparatus, a traveling label carrier adapted to support a succession of labels and deliver them into the path of movement of containers, a rotatable picker for delivering and positioning labels on the 85 carrier, means for retaining the carrier travel path in proximity to the picker during normal operating conditions, and control mechanism for said means operative to shift the carrier path under abnormal 90 conditions.

132. In labeling apparatus, a traveling label carrier adapted to support a succession of labels and deliver them into the path of movement of containers, a rotatable picker 95 for delivering and positioning labels on the carrier, means for retaining the carrier travel path in proximity to the picker during normal operating conditions, and control mechanism for said means operative to 100 shift the carrier path under abnormal conditions, said means including a piston and cylinder adapted to produce a chamber of variable dimensions, suction-creating mechanism adapted to communicate with said 105 chamber to provide relative movements between piston and cylinder, and means whereby such relative movements are communicated to the carrier.

133. In labeling apparatus, a traveling 110 label carrier adapted to support a succession of labels and deliver them into the path of movement of containers, suction-creating mechanism, a rotatable picker operatively connected to such suction-creating mechanism for delivering and positioning the labels on the carrier, a piston and cylinder adapted to produce a chamber of variable dimensions, connections between the chamber and the suction-creating mechanism for providing 115 relative movements between the piston and cylinder, and means controlled by the relative movements of piston and cylinder 120 and operative on the carrier for shifting the carrier travel path. 125

134. In labeling apparatus, a traveling label carrier adapted to support a succession of labels and deliver them into the path of movement of containers, suction-creating mechanism, a rotatable picker operatively 130

connected to such suction-creating mechanism for delivering and positioning the labels on the carrier, a piston and cylinder adapted to produce a chamber of variable 5 dimensions, connections between the chamber and the suction-creating mechanism for providing relative movements between the piston and cylinder, and means controlled by the relative movements of piston and 10 cylinder and operative on the carrier for shifting the carrier travel path, said picker having a label-receiving face operatively connected to the suction line in label-feeding position, whereby maintenance of the suction 15 line to the picker during normal label feeding operation will move said latter means to position the carrier to travel in juxtaposition to the picker face, venting of the suction line through imperfect label feed 20 permitting relative movement of piston and cylinder to cause shifting of the carrier away from such normal travel path.

135. In labeling apparatus, a traveling label carrier adapted to support a succession of labels and deliver them into the path of 25 movement of containers, a rotatable picker for delivering and positioning labels on the carrier, means for retaining the carrier travel path in proximity to the picker during normal operating conditions, and control mechanism for said means operative to 30 shift the carrier path under abnormal conditions, said means including a piston and cylinder adapted to produce a chamber of variable dimensions, suction-creating mechanism adapted to communicate with said 35 chamber to provide relative movements between piston and cylinder, and means whereby such relative movements are communicated to the carrier, said control mechanism 40 including a valve structure in the suction line.

In testimony whereof I affix my signature.
JONATHAN PETERSON.
